UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

AUTOMATIC COMMON-BATTERY PARTY-LINE TELEPHONE SYSTEM.

1,151,546.

Specification of Letters Patent. Patented Aug. 24, 1915.

Application filed February 3, 1906. Serial No. 299,268.

To all whom it may concern:

Be it known that I, TALBOT G. MARTIN, a citizen of the United States of America, and resident of Chicago, Cook county, Illinois, **5** have invented a certain new and useful Improvement in Automatic Common-Battery Party-Line Telephone Systems, of which the following is a specification.

My invention relates to automatic or semi-**10** automatic telephone systems in general, but more particularly to systems in which the subscribers are provided with switch devices for sending the electrical impulses necessary for operating the electrically-propelled and **15** step-by-step-actuated trunk-selecting and line-connecting switching machinery at the exchange or central station, and especially to telephone systems in which one or more of the subscribers' lines are used as party-**20** lines.

In certain respects my invention is in the nature of an improvement on the party-line telephone system disclosed in my prior application No. 289,048 filed by me in the **25** United States Patent Office on the 25th day of November, 1905, and in which application I have set forth an automatic party-line telephone system employing local batteries for charging or operating the microphone **30** transmitters at the subscribers' stations.

Generally stated, therefore, the object of my present invention is the provision of an improved and highly efficient automatic party-line telephone system of the foregoing **35** general character.

Special objects of my invention are the provision of an improved construction and arrangement whereby the features of my said prior invention may be combined with **40** and adapted for use in conjunction with a common battery or centralized source of talking current; and the provision of certain details and features of improvement and novel combinations, all tending to increase the general efficiency and serviceability **45** of a telephone system of this particular character.

To the foregoing and other useful ends, my invention consists in matters hereinafter **50** described and claimed.

In the accompanying drawings Figure 1 is a diagrammatic representation of two connected party-lines in an automatic telephone system embodying the principles of **55** my invention. One of said lines is provided

with two substations numbered 320 and 220, respectively—which are bridged between the main line-conductors—the other line being similarly equipped with substations 130 and 230, respectively. In said figure the sub-station #320 is represented as calling the sub-station #130 through a calling first-selector A, a connector C, and the first-selector A¹ of the called line. Since all of the sub-stations are identical, and since they are all similarly represented, it will be sufficient to describe only one. Fig. 2 is a diagrammatic perspective view showing the approximate relative positions of the parts of the first-selector A, the switch-frame of which is not **60** shown. Fig. 3 is a similar view of the connector C. Fig. 4 is a view similar to Fig. 1, in which the subscriber at sub-station #320 has called the subscriber at sub-station #120 on the same line where a third sub-station **70** #220 is bridged across the line between the former two.

All of the sub-stations are provided with the usual details essential to automatic sub-stations of the class in question. Sub-station #320, for instance, is provided with a receiver 2 and a switch-hook 3 which has radiating from its body a number of cam-arms 4, 5, 6 and 7. Said hook is suitably pivoted on the so-called sub-station keyboard-frame which carries most of the mechanical details of the telephone. As usual, the switch-hook is raised or lowered whenever the receiver is removed or restored to its place. The said hook is raised or lowered to accomplish certain switching operations to be disclosed, and for controlling certain mechanical details that will be hereinafter described. Furthermore, said sub-station has a transmitter 8, a ringer 9, and **80** an induction-coil 10 with primary and secondary windings 11 and 12, respectively; also a couple of condensers 13 and 14, a signaling device composed of a push-button 15, a spring 16, and two contact-points 17 and **85** 18 whereby one side of the main line may be grounded; and in addition a relay 19 under the control of which are found the springs 20, 21, 22 and 23. When the switch-hook is down the cam-arm 5 is held in contact with the spring 24, whereby said spring is retained at such time in a downwardly-fixed condition. Said spring and cam-arm are, therefore, normally in contact, and in this **90** way a circuit is completed from the line **95** 110

through the ringer 9, which circuit includes, besides the said ringer 9, the ringer-circuit-spring 24 and condenser 13.

Associated with the ringer-circuit-spring 24 are two sets of springs 26 and 27, and 28 and 29. The members of each of these sets, when left to their own tension—that is, when the switch-hook is up—engage in contact with each other; the springs 26 and 27 being in contact, and the springs 28 and 29 being in contact; and whenever the switch-hook depresses the spring 24 the latter permits the springs 27 and 29, respectively, to separate from the springs 26 and 28. The cam-arm 7 controls the springs 30, 31, 32 and 33 of which the members 30, 31, 31 and 32 are retained out of engagement with each other, and the spring 32 in contact with the fourth spring 33; but when the switch-hook is up the first three springs are forced together by the said cam-arm 7. Furthermore, while the switch-hook is down the springs 34 and 35 are kept apart by the cam-arm 6, but when it rises the said springs flex into contact. There are three other springs 36, 37 and 38 under the control of the cam-arm 4, which springs are known as the release-springs, and are forced into engagement by the said cam-arm when the latter engages a laterally-projecting piece 39 at the upper extremity of the spring 38. However, when the switch-hook nears its lowermost position said arm disengages from said spring and permits the said release-springs to again disengage. The calling device comprises two push-buttons 40 and 41, two springs 42 and 43, two contact-points 44 and 45 and a so-called ground-post 46 against which the springs 42 and 43 may be pressed to ground either or both sides of the main line. The sub-station relay 19 is suitably mounted upon the keyboard or switch-frame. This relay is provided with an armature 47 by means of which, when the relay is magnetized, the springs 20 and 22, respectively, are separated from the springs 21 and 23. Furthermore, said relay has on its under side an armature locking device that consists preferably of a metal piece 48 which, normally, is vertically disposed and which is riveted to a spring 49 that is fastened to the rear of the relay frame. The front end of said metal piece is bent at a right angle horizontally and to the front; and whenever the armature 47 is attracted by the magnet the tension in the spring 49 forces the metal member upward until the angled section rises in front of the armature 47, locking the latter in its attracted position. The switch-hook also carries a slim link-rod 50 that passes through a guide-hole in a piece suitably secured near the front part of the relay. The lower end of said link works in front of the armature 47 and is bent at a right angle horizontally

and in a plane parallel to the plane of the armature. When the switch-hook is depressed the said link 50 descends far enough to drive the lock 48 below the edge of the armature 47, which latter then, if the magnet is not energized, resumes its normal position as shown at sub-station #320, Fig. 1. When the said armature is restored the relay-springs 20, 21, 22 and 23, of course, re-engage.

In Fig. 2, the first-selector A is shown with the bank 75 of trunk-line-terminals beneath said selector, while the private-bank 76 is located just above the trunk-line bank. The switch-shaft 77 is vertically disposed on the front of the switch-frame and is retained connected therewith by bearings which are not shown. The shaft may be moved longitudinally in said bearings, and then rotatively, by ratchet and pawl electro-magnetically-operated devices, the vertical or longitudinal movements occurring first. Among the functions of the shaft an important one is that of holding the line-wipers 78 and 79 and the private-wiper 80. The first two 92 comprise a set distinct from the latter, but both sets are located within range of the contacts of their respective banks 75 and 76. Said wipers are not only insulated from the shaft, but from each other as well. Among 95 the details that are associated with the shaft is a cam piece 81 which is of a split sleeve design and secured to the shaft by a screw 82. The general shape of said cam, in cross-section, is that of an oval with the smaller 100 end on the side farthest away from the said screw. Said cam abuts on a hub 83 which is shrunk to the shaft near the middle of the latter. This hub carries a set of longitudinal teeth 84 that serve, as will be disclosed, to enable the forward rotation of the shaft, and as a means of locking the same 105 against backward rotation. On the neck portion of said hub there is formed a set of circular teeth 85 that serve in turn as a 110 means by which the raising of the shaft is accomplished, and for locking it when raised. These circular teeth are traversed by a groove 86 into which the end of a so-called shaft-rest 87 normally projects; but 115 when the shaft is rotated, any one of the said circular teeth which may be at the proper height slides onto the end of said rest. The end of said rest is, of course, adapted to fit circular grooves between said 120 circular teeth. The upper surface of the engaging end of the rest is level, but the under side is chamfered to form a bevel that corresponds to the upper slope of the circular teeth.

Above the hub 83 the shaft carries an arm 88 known as the normal-post-arm, which, while the switch-shaft is at rest and while the shaft-rest occupies the slot 86, is retained against the normal-post 89 by the 130

coil-spring 90. Said arm 88 exercises control over the so-called shaft-springs 91 and 92, so that when the shaft is raised said springs, which are normally separated, are permitted to come into contact. Among the magnets allotted to the first-selector some are used as relays and others as operating magnets. The magnets 93 and 94 are among the former kind and are known, respectively, as the vertical and rotary line-relays. Said relays, by means of their respective armatures 95 and 96, control the springs 97 and 98 with respect to the ground-spring 99. All of said springs are comprised in energizing circuits of operating magnets that operate the shaft. The magnet 100, armature 101 and springs 102, 103 and 104 constitute the so-called bridge-cut-off-relay. The magnet 105, with its armature 106 and springs 107 and 108, constitutes the back-release-relay, and is used for restoring the switch after the latter has seized a trunk-line and when such release is desired. Of the operating magnets the magnet 109 is known as the vertical-magnet, and has allotted to it a so-called vertical-armature 110 supported by pivots 111 beneath said vertical-magnet. Whenever the coils 112 and 113 of said magnet become energized the armature 110 is attracted, and when the magnetism ceases the retracting-spring 114 restores said armature to its normal position. The upward movement of the armature is limited by the pole-pieces of the magnet-coils 112 and 113, and the lower limit is marked by a section of the switch-frame that passes under the arm 115. Said arm is known as the vertical-arm and extends forwardly from the vertical-armature 110, of which latter it is a part. The vertical-arm carries on its end a so-called vertical-pawl 116 which, when the vertical-armature is attracted, engages with some one of the circular teeth 85 to raise the shaft. Normally, the under surface of the upper section of said pawl rests against a piece that is secured to the switch-frame and that retains the pawl away from the circular teeth. When the vertical-armature is attracted, as the pawl rises, a retracting-spring 117 thrusts the upper side of the pawl toward the circular teeth 85. As soon as said pawl clears its normal-rest, and by the time that the vertical-armature strikes the pole-pieces, the vertical-pawl strikes, with the rear surface of its upper section, a bumper piece which constitutes a part of the switch-frame. Therefore, the shaft is prevented from being raised unduly by its own momentum—that is, more than one notch at a time. It is clear, then, that the pawl 116 not only raises the shaft, but that it also acts as a lock at the end of each stroke. The vertical-arm has also an L-shaped piece 118 on its under edge that engages a so-called release-

link 119 of flexible spring material. Said link carries an aperture 120 on its front end, and is secured to the armature 121 of one of the operative magnets 122, known as the release-magnet. Said armature is suspended from the frame by the supports 123, and is normally retained by the spring 124 away from the pole-piece of the release-magnet. A stop is suitably provided behind said armature to limit its movements when retracted. The first-selector is provided with a peculiarly shaped device 125 known as the double-dog which is pivoted so that it may swivel about a vertical axis that passes through the pivots 126. On its front side said double-dog divides into two dogs 127 and 128, so situated and constructed that the dog 127 may operate in conjunction with the circular teeth 85 while the switch-shaft is raised and in normal rotary position, and so that the dog 128 may lockingly engage the longitudinal teeth 84 when the shaft is rotated. To the right of the pivots 126 the body of the double-dog extends rearwardly, and projecting down therefrom is an arm 129 that comes into play very prominently during the releasing of the switch. Near the extremity and on the upper side thereof the body of the double-dog has a pin or lug 130 that projects upwardly. Said lug is normally caught in the aperture 120 of the release-link 119, and then because of the tension in the spring 124 the dogs 127 and 128 are retained away from the shaft. Each time the vertical-magnet 109 is energized, it operates the shaft longitudinally one step by means of the armature 110. At the first step of the vertical-armature, the link 119 is drawn away from the lug 130 by the piece 118, and then the double-dog is rotated by the retracting-spring 131, so that the dog 127 falls under the first circular tooth, and so that when the vertical-armature returns to its normal position the said shaft will be retained by said dog in its new position. The release-link 119, while the double-dog is free, rests with its end upon the lug 130, but out of locking engagement therewith. When the vertical-armature is attracted a second time, the shaft is raised a second step, and the dog 127 at the second stroke passes from under the first tooth to a position under the second tooth holding the shaft again, as before.

The release-magnet 122 is composed of two coils, like the vertical-magnet 109, but, for convenience of illustration, only one coil is shown. If, while the shaft is raised, the said release-magnet should be energized the release-armature 121 is attracted and the release-link 119 is thrust forward to catch the lug 130 in the aperture 120. Upon the deenergization of the release-magnet the retracting-spring 124 then withdraws the dogs 127 and 128 from engagement with the

shaft-teeth, and the shaft being thus deprived of its temporary support falls to normal position by its own weight. After the shaft is once raised it may be rotated by a second operating magnet 132 known as the rotary-magnet. Said magnet has two coils 133 and 134 and, unlike the vertical-magnet, has its armature 135 pivoted in a vertical plane. Said armature may be moved about a vertical axis that passes through the pivots 136. The limit of the movement of said armature toward the rotary-magnet is determined by the pole-pieces of said magnet, which movement is produced by the rotary-magnet itself. The motion of the armature in the opposite direction is produced by the retracting-spring 137, and is limited by a stop piece (not shown) behind the so-called rotary-arm 138. This arm, like the vertical-arm, carries a so-called rotary-pawl 139. Said rotary-pawl normally rests against a stop that retains it away from the longitudinal teeth, and when the rotary-armature is attracted it is drawn into engagement with the longitudinal teeth by a spring 140 attached to the rotary-arm by one end and to the rear of said pawl by the other. By the time that the rotary-armature strikes the pole-pieces of the rotary-magnet, the rotary-pawl also strikes a bumping post, as does the vertical-pawl, and locks the shaft against further advance by the force of its own momentum. At the end of the first rotary step the dog 128 falls behind the first longitudinal tooth, so that when the rotary-pawl falls back the shaft is retained. It should be evident that as the shaft is rotated the vertical-dog 127 is extricated from the groove of the circular tooth below which it has been resting, by the passage of the rotary-dog 128 across the longitudinal tooth over which it has to slide at the time; but at the beginning of the rotation the tooth has been caught by the vertical-dog slides onto the shaft-rest 87, and the shaft is thus provided with a new support in lieu of the vertical-dog 127 and is still held raised after the rotation begins. The rotary-armature is provided with a so-called interrupter-finger 141 that separates the interrupter-springs 142 and 143 whenever the rotary-armature is attracted, and also with a rotary-armature-finger 144 that exercises certain controlling influences over the armature 145 of one of the operating magnets, namely the private-magnet 146. The said private-armature 145 works in a vibratory manner about a horizontal axis that passes through the supporting points 147. This armature is formed with a forwardly-projecting arm 148, the latter having two flat surfaces in an approximately horizontal plane. Furthermore, the end 149 of the arm 148 is bent downwardly at a right angle, and said arm 148 carries certain mechanical

details, namely a lateral arm 150 which is designed to control circuits comprising the private-springs 151, 152 and 153, and a tooth-escapement which includes two flexible springs 154 and 155 each of which is riveted by one end to the arm 148, one on the upper side and the other on the lower. The upper spring is straight and has formed on its end two tooth projections 156 and 157 which extend downwardly, while the lower one is bent down and at a right angle again to the front. This double angle on the lower spring is so designed that the latter may clear the bent portion 149 of the private-arm, against which portion the said spring rests with a degree of tension, and so that space is afforded in front of said bent portion to receive two other tooth-shaped upwardly-projecting pieces 158 and 159 that are formed on the forward end of the escapement-spring 155, and which are sustained in juxtaposition to the upper teeth, but slightly to the rear thereof. A retracting-spring 160, suitably located, holds said armature normally away from the private-magnet pole-piece. A well-known auxiliary switching mechanism common to such switches is the so-called side-switch. It is shown in connection with the first-selector A and comprises an arm 161 which is secured to the switch-frame in such a manner that it may be made to swivel about a vertical axis that passes through the pivots 162. The right extremity of said arm is drawn out into a finger 163 that works in conjunction with the escapement-teeth previously described. Said teeth, in a manner to be explained, convert the outward movement of the side-switch into a step-by-step motion, which movement is produced by a retracting-spring 164.

At the base of the finger 163 a lug 165, which is bent to the front, is adapted to strike the cam 81 at a suitable time. Whenever the shaft is rotated, however, said cam is carried beyond the reach of the said lug, and after that the finger 163 simply falls against the tooth 159. Near its left extremity the arm 161 carries a number of wipers 166, 167, 168 and 169 suitably mounted upon a pin 170 and insulated therefrom and from each other. Said wipers are known as the side-switch-wipers, and are adapted to be operated by the private-magnet and escapement device previously described. If the private-magnet is energized once, the private-armature is drawn down once and then restored to its normal position. The escapement-finger 163 passes from behind the tooth 158 onto the rear of the tooth 156, upon the downward stroke of the private-armature 145, and from behind the latter tooth upon the return stroke. As soon as the escapement-finger clears or disengages the latter tooth, the retracting-spring 164

draws the side-switch to the second position where it is stopped by the lug 165 when it strikes the cam 81. Immediately, then, as will be shown, the rotary-magnet becomes 5 energized, the shaft is rotated, and the cam passes out of reach of the lug 165; and the finger 163 of necessity falls against the tooth 159, because of the tension in the spring 164. The rotation of the shaft results when the 10 rotary-armature 135 is attracted by the rotary-magnet: at the same time, however, the rotary-armature-finger 144 depresses the private-armature 145 and causes the finger 163 to disengage from the tooth 159 and to 15 advance against the tooth 157, and then, as the rotary-armature returns to normal position, when the rotary-magnet deenergizes, the private-armature, upon following the finger 144, permits the escapement-finger 20 163 to escape from the last tooth 157, at which instant the side-switch passes to third position with the said finger resting against the side-switch-stop 171. In their normal positions, the side-switch-wipers 166, 167, 25 168 and 169 engage, respectively, with the contact-points 172, 173, 174 and 175. This position is known as the first position of the side-switch, at which time it will be seen that the finger 163 is held behind the 30 escapement-tooth 158. In the second position, while the said finger is between the teeth 159 and 158, the said side-switch-wipers engage instead with the contact-points 176, 177, 178 and 179, respectively; 35 and when the said finger 163 falls against the stop 171, the wipers change their positions and move into contact with the contact-points 180, 181, 182 and 183, respectively. Between the pivots 162 and the wipers-supporting pin 170, a rearwardly-extending arm 40 184 on the side-switch-arm 161 supports on its end, pivotally, one end of a link 185; the other end of which latter, being bifurcated, engages with the lower end of the 45 double-dog-arm 129, which latter is constructed somewhat in the shape of an inverted T. Should the release-magnet be energized while the side-switch is in third position, and, of course, while the shaft is 50 rotated, the release-link 119, being attached to the release-armature 123, is thrust forward and catches the lug 130 in the aperture 120. Then when said release-armature is restored, the spring 124, as before described, with- 55 draws the dog 128 from the longitudinal ratchet-teeth 81. At the same time, the arm 129 drives back the link 185, which latter then rotates the side-switch-arm 161 about the pivots 162, against the tension of the 60 side-switch retracting-spring 164, and thus drives the finger 163 between the springs 154 and 155 and into a position behind the tooth 158, locking the side-switch in the first or normal position. The switch-shaft being un- 65 locked by the removal of the dog-support 128, and being thus left free, is rotated by the coil-spring 90 until the end of the shaft-rest enters the slot 86, at which time the shaft drops to its normal position. Therefore, after the switch has been operated, the 70 energization and deenergization of the release-magnet is sufficient to restore the switch completely to its normal position. The first-selector is also provided with a vertical-private-normal-relay 186, and with a 75 rotary-private-normal-relay 187. Each of these relays, by means of their corresponding armatures 188 and 189, has control of a set of two springs 190 and 191, and 192 and 193, respectively. These armatures, and the 80 armatures 95, 96, 101 and 106 of the line and bridge-cut-off and back-release relays are similarly and suitably pivoted from points at their elbows; and when the magnet to which the armature is allotted is energized 85 the end of said armature is operated so that it travels away from the magnet. It is common practice, in using these first-selectors, to allot one to each line. With such arrangement, the subscriber line-conductors usually 90 terminate normally in side-switch-wipers similar to the side-switch-wipers 168 and 169, the vertical side of the line terminating in a wiper corresponding to the side-switch-wiper 168, and the rotary side of the line terminating 95 in a wiper corresponding to the side-switch-wiper 169. In this system, however, and although the vertical side of the line terminating in the first-selector A leads to the side-switch-wiper 168, the rotary side 100 ends in the switch-shaft-spring 92; but when the switch-shaft is raised and the springs 92 and 91 are brought into contact the rotary-line-conductor is extended to the usual side-switch-wiper 169. 105

The connector is of a well-known general type and adapted to perform the duties allotted to it in this system. Many of the mechanical operations, as well as many of the circuits are very similar to those of the first-selector, and the general movements are nearly identical. The line and private banks will be at once recognized, as well as the vertically-disposed switch-shaft 200. Being identical with the first-selector switch-shaft, the latter is provided with the line-wipers 201 and 202, private-wiper 203, cam 204, longitudinal and circular ratchet-teeth 205 and 206, respectively, the normal-post-arm 207, and the coiled spring 208. 110 The said circular ratchet-teeth, it will be seen, are traversed by the usual longitudinal slot 209 into which the end of the shaft-rest 210 projects. The normal-post-arm 207 has under its control a spring 211, which, while the shaft is down, is kept out of contact with the contact-point 212, but with which latter it engages when the shaft is in operation. The vertical movement of said shaft is, of course, produced through the 115 120 125 130

medium of the vertical-magnet 213, which latter, as usual, is provided with a vertical-armature 214, having a vertical-arm 215, and a vertical-pawl 216, the said vertical-arm being supplied with the L-shaped piece 217. The release-magnet 218, unlike the release magnet of the first-selector, has its armature 219 on the right side instead of on the left side, which armature is constructed 5 with an elongated front member 220 that reaches as far as the middle section of the double-dog 221. The release-link 222 is, as usual, under the control of the L-shaped piece 217, but is permanently secured to the 10 switch-frame at the inner end 223. The vertical and rotary locking-dogs 224 and 225, respectively, of the double-dog 221, will be recognized, as well as the side-switch releasing-arm 226 and, on the upper side of 15 the body of said double-dog, the lug 227 which is caught by the release-link 222 in the aperture 228. Whenever the release-magnet of the connector is energized, the release-link 222 instead of being thrust for- 20 ward to catch the said lug 227 remains where it is and the double-dog 221 is engaged at a point to the right of the bearings 229 by the end 220 of the armature 219, and thereby rotated to normal position—like 25 the double-dog of the first-selector—so that the lug 227 is driven under the aperture 228, in which latter the lug is caught by the release-link 222 as stated. The double-dog 221 when thus locked is prevented from re- 30 turning to its operative position when the release-magnet becomes deenergized. The rotary-magnet 230 has a rotary-armature 231 that is quite simple. This latter is pro- 35 vided with a rotary-arm 232 upon the ex- tremity of which the rotary-pawl 233 is lo- 40 cated. The rotation of the shaft each time that the rotary-magnet is energized is pro- 45 duced in a manner similar to that described in connection with the first-selector. The private-magnet 234, private-armature 235, 50 springs 236 and 237, escapement-teeth 238, 239, 240 and 241 and the arm 242 are identi- 55 cal with similar parts of the first-selector. The said arm 242, however, controls the 60 private-springs 243, 244, 245 and 246, so that when the private-armature 235 is down the first two of said springs are separated and the last two brought into contact; and when the said armature is up the reverse takes 65 place—that is, the springs 243 and 244 close and the springs 245 and 246 separate. In the side-switch of the connector the side- switch-arm 247, escapement-finger 248, cam-lug 249, side-switch-stop 250, retracting- 70 spring 251 on one side of the pivots 252, member 253, link 254, side-switch-wipers 255, 256, 257 and 258, together with their corresponding contact-points 259, 260 and 261; 262, 263 and 264; 265, 266 and 267; 75 and 268, 269 and 270 on the other side, con-

form to like parts of the first-selector side- switch. Among the relays of the connector the vertical-line-relay 271, by its armature 272, can flex the spring 273 against the grounded spring 274 and the spring 275 70 toward the spring 276, when said relay is energized. The rotary-line-relay 277, in the same manner, by its armature 278, when said relay is magnetized, forces the spring 279 against the same ground-spring 274 and permits the spring 276 in turn to bend toward the spring 275. Said two springs 75 275 and 276 are so adjusted that they come into contact only when the two armatures 272 and 278 are attracted simultaneously. 80

The ringer-relay 280 is a feature common to all connectors of the type under consideration and is adapted when energized to disconnect the terminals of the called line from those of the calling line and to place 85 across the former the terminals of the ringer-generator J. This operation is accomplished through the medium of the armature 281 which has control of the ringer-relay-springs 282, 283, 284, 285, 286, 287, 288 and 289, some of which are the 90 terminals to which reference is made above. In addition, the connector is provided with a differential-relay 290 having two windings 291 and 292. One end of the said winding 95 292 is connected through the vertical-line- relay 271 with the vertical side of the main talking line, and the other end of said winding is connected with the non-grounded 100 terminal of battery B. The second winding 291 is connected at one end through the rotary-line-relay 277 with the rotary side of the main talking line, while the other end is connected with the ringer-relay-spring 105 288 of the ringer-relay 280. Said spring 288 is normally in contact with a second 110 spring 289 that is connected with a third spring 293 which is under the control of the armature 294 of the so-called pole- changing-relay 295. Furthermore, said 115 spring 293 is located between two other springs 296 and 297 and is normally in contact with the latter which constitutes the non-grounded terminal of battery B, but the 120 said middle spring 293 may be shifted by the armature 294 away from the spring 297 and into contact with the spring 296 which, when the connector-side-switch is in third position, is directly connected with ground. By means of such construction the differ- 125 ential-relay-coil 292 may be energized only when the vertical side of the main line is connected to ground; but the other coil 291 may be energized when the rotary side of the line is grounded or when the spring 293 is grounded against the spring 296—that is, while the side-switch-wiper 256 is in third position. In one case the current will flow in one direction, and in the other case in the opposite direction, in this last coil, so that 130

the two windings 291 and 292 may be energized to neutralize or reinforce each other, depending upon the direction in which the current is made to flow. Also, with the arrangement described, the two ends of the coil 291 may be grounded at the line and at the spring 293 simultaneously, rendering said coil or winding, together with the rotary-line-relay 277, short-circuited or shunted through ground for purposes to be disclosed hereinafter. Said differential-relay can, when energized, and by its armature 298, separate the springs 299 and 300 and close the springs 301 and 302. The former 15 normally rest in contact and the latter out of contact. In addition, the connector is given a retardation-coil 303 which is used to balance the line and to regulate the flow of current in circuits in which said coil may be included. There are also two condensers 304 and 305 which are included in the main talking circuit, one on the one side of the line and the other on the other.

In Fig. 1 the called first-selector A' being identical with the calling first-selector A, the former will be recognized without further description. For the sake of simplicity, however, the private-normal-relays (similar to the private-normal-relays 186 and 187 of the first-selector A) have been omitted, but the springs 306, 307, 308 and 309 which they control are shown. Hereinafter it will be disclosed how the bridge-cut-off-relay 310 is maintained energized while a connector is connected with the called line. The purpose for so keeping said relay energized is temporarily to destroy or open a bridge that normally exists between the side-switch-contact-points 311 and 312 and that includes the line-relays 313 and 314 in series with the bridge-cut-off-relay-springs 315 and 316, by separating the spring 317 from the said springs 315 and 316, which spring 317 is connected to the non-grounded terminal of battery B. The object in this construction is well known.

To a full understanding of the construction and operation of the various parts of my invention, and the circuits involved when one subscriber calls another subscriber, a description will now be given of the process by which the subscriber #320 calls or connects with and rings or signals the subscriber at station #130. In order to make a call the subscriber at the sub-station #320 first removes his receiver 2 from the switch-hook 3; then the cam-arm 5 disengages from the ringer-circuit-spring 24, and the normally-closed circuit through the ringer 9 at the sub-station #320 is opened. Furthermore, as soon as said cam leaves the spring 24 the springs 26, 27, and the springs 28, 29 come into contact. At the same time the spring 32 leaves the spring 33 and is driven into electrical connection with the

springs 31 and 30 by the cam-arm 7. Furthermore, the so-called ground-springs 34 and 35 are permitted to engage as soon as the cam-arm 6 passes away from the ground-spring 35. At once a ground connection is completed between the ground-post 46 and the ground-terminal G'. The said connection may be traced from the said ground G' through the sub-station relay-springs 21 and 20 to the conductor 318, thence to the ground-springs 35 and 34 and over the conductors 319 and 320 to the said ground-post. The subscriber then proceeds to establish his connection by pressing the vertical-button 40 once, and then the rotary-button 41 once, by which operations the first-selector extends the subscriber's line through some idle trunk to the connector C. At the next movement the operator presses the vertical-button 40 again three times, and the rotary-button 41 once. By this the connector-switch-shaft is raised to the level (the third level) in which is found the terminal of the desired subscriber's line, and then at the grounding of the rotary line the side-switch 85 passes to second position. The calling subscriber proceeds by pressing for the last time the vertical-button 40 ten times, and the rotary-button 41 once, thereby causing the connector-wipers to be rotated into connection with the desired line, causing the extended line-conductors to be connected with said wipers, and thus completing the desired connection. When the vertical-button 40 is pressed once for the first time the vertical-line-conductor 321 is thereby grounded once and the vertical-line-relay 93 of the first-selector A is energized once. The current in this energizing circuit passes from ground G' through a circuit already described, to the ground-post 46, thence to the spring 42, vertical-line-conductor 321, vertical-side-switch-wiper 168, contact-point 174, conductor 322, vertical-line-relay 93, conductor 323, bridge-cut-off-relay-springs 103 and 104 110 to the battery-lead 324, and through battery B to ground G. Upon being energized, the vertical-line-relay attracts its armature 95, and forces the line-relay-springs 99 and 97 into contact, by which operation the vertical-magnet 109 is in turn energized. The current in this last energizing circuit passes from ground G' through the said springs 99 and 97, conductor 325, private-springs 152 and 151, conductor 326 and vertical-magnet 120 109 to the battery-lead 324, thence through battery B to ground G. Upon being magnetized the vertical-magnet attracts the vertical-armature 110 once and raises the switch-shaft one step. At this step, of course, the release-link 119 is withdrawn from the double-dog 125 by the L-shaped piece 118, at which time the dog 127 engages one of the circular teeth 85 and prevents the shaft from falling to its original position. 130

At the time that the normal-post-arm leaves the spring 91, the latter passes into engagement with the contact-point 92, and the rotary-line-conductor 327 which is normally 5 open at the said contact-point 92 is then extended to the rotary-side-switch-wiper 169. After the shaft has been raised one step in this manner the switch-wipers will be found opposite the first contact of the first level 10 of their respective banks 75 and 76, but out of engagement with the bank-contacts. The rotary-button 41 is then pressed once, and the rotary-line-relay 94 becomes energized once. The current in this case passes again 15 from ground G¹ to the ground-post 46 and thence to the spring 43, rotary-line-conductor 327, springs 92 and 91, conductor 328, side-switch-wiper 169, contact-point 175, conductor 329, rotary-line-relay 94, conductor 330, bridge-cut-off-relay-springs 102, 103 and 104 to the battery-lead 324, and through battery B to ground G. The rotary-line-relay being energized, the line-relay-springs 98 and 99 are forced into contact, and as a result the private-magnet 146 20 is magnetized. The electric current here flows from ground G² through the springs 99 and 98, conductors 331 and 332, and private-magnet 146 to the battery-lead 324, thence through battery B to ground G. The 25 private-armature 145 being attracted once and restored, the escapement-tooth 158 first clears or disengages the escapement-finger 163, which latter then falls against the second tooth 156, and when the armature returns to its normal position the latter tooth in turn clears or disengages the escapement-finger 163. At that instant the side-switch 30 is drawn into second position by the retracting-spring 164, with the cam-ing 165 resting against the cam 81.

It will be understood that the prongs of the bifurcated end of the link 185, which rest upon the T-shaped extremity of the 35 side-switch releasing-arm 129, are of sufficient length to permit the said releasing-arm 129 to move from the position that it holds when the double-dog is held normally locked by the release-link 119 to the position it assumes when the double-dog is released, without disengaging from said prongs. The moment that the side-switch passes from first to second position a circuit is completed through the rotary-magnet 40 45 50 55 60 65 70 75 80 85 90 95 100 105 110 115 120 125 130 135 140 145 150 the grounded terminal G⁴, side-switch-wiper 167, conductor 336, back-release-relay 105, conductor 337 and private-wiper 80. Furthermore, by the same ground connection G⁴, and through the side-switch-wiper 167, conductor 338, private-normal-relay-springs 193 and 192, and private-normal-conductor 339, a guarding potential is established at the connector-private-bank corresponding to the calling line, that no calling subscriber may interfere with the calling line for the time being. Similarly, should any first-selector appropriate to its use a second trunk-line of the same level of the line-bank 75, a guarding potential will then appear at the second private-contact of the first level of the private-bank 76, as well as at all other private-contacts in multiple. And should a third first-selector seize the third trunk on the same level a guarding potential will appear also at the third private-contact of the first level; and if the fourth, fifth, etc., through the nine trunks be occupied, guarding potentials will be found at the fourth, fifth, etc., and through the ninth private-contact-terminals of the first level of the private-bank. Therefore, if the first nine trunk-lines of the first level are busy a guarding potential is found at each one of the first nine private-contacts of the first level of the private-bank 76. If this condition exists at the time that the calling subscriber #320 grounds the rotary-line-conductor by pressing the button 41—some other subscriber, of course, holding the first trunk of the first level—the rotation of the shaft will not terminate as soon as the wipers move onto the first terminal of the first level. The first nine private-contacts being grounded, then when the calling subscriber grounds the rotary side of the line, as described, the side-switch trips into second position as before; but the rotation of the shaft does not cease until the wipers have been carried beyond the last of the busy trunk-lines, in this case onto the tenth terminal of the first level of the banks in question. This continued or selective rotation takes place in the following manner: The energizing circuit through the rotary-magnet being closed as pointed out, at the juncture when the side-switch-wiper 166 engages with the contact-point 176, the rotary-armature is attracted by the rotary-magnet 132, and the shaft is rotated one step, in the manner described, so that the line and private wipers are carried into engagement with the first terminal of the first level of their respective banks. At the same time the private-armature is depressed by the rotary-armature-finger 144, and the interrupter-springs 142 and 143 are, at the end of the stroke, separated by the interrupter-finger 141. There being a guarding potential at the first contact which the private-wiper meets, a circuit is thereby completed through the private-magnet 146, which extends from the ground terminal G of the battery B, through the private-wiper of whatever first-selector is occupying the first trunk of the first level in question, through the bank-multiplying conductors to the contact-point with which the private-wiper 80 is in engagement, through conductor 337, winding of the back-release-relay 105, conductor 336, side-switch-wiper 167, contact-point 177, conductors 340 and 332, private-magnet 146, and through battery B to ground G. The private-armature is thereby retained in a depressed condition, even after the energizing circuit of the rotary magnet is broken at the interrupter-springs, and while the rotary-armature-finger returns to its normal position in response to the retracting tension of the rotary-armature-retracting-spring 137, since the escapement-finger 163 is held by the upper foremost escapement-tooth 157. The side-switch-wiper 166 being, therefore, retained in engagement with the grounded contact-point 176, it follows that as soon as the interrupter-springs come together the energizing circuit through the rotary-magnet is completed once more. As a result, the rotary-armature is again attracted, the shaft is rotated one more step, and the private-wiper is moved onto the second terminal of the first level of the private-bank 76. Said second contact also being grounded, it follows that the energizing circuit through the private-magnet is maintained, so that the side-switch is not liberated when the rotary-armature again returns to its normal position. Clearly, then, the shaft will be rotated in a step-by-step manner as long as the private-wiper continues to meet with grounded private-contacts. After being rotated onto the ninth contact the private-wiper is rotated one more step into engagement with the tenth contact of the first level of the private-bank; but this last contact being devoid of guarding potential, it is evident that as soon as said wiper leaves the ninth contact and passes onto said contact this magnetizing circuit through the private-magnet is broken. This occurs at just about the time when the rotary-armature is at the end of its attractive stroke; so that the private-armature that has up to this time held the side-switch in its second position (by the magnetizing force which has now disappeared from the private-magnet) falls back upon the rotary-armature-finger 144 and follows said finger as the rotary-armature returns to its normal position. Between the time that the private-armature is released by the private-magnet and the time that the rotary-armature fully regains its normal position the escapement-finger 163 which, during the rotation of the shaft, 130

has been resting against the foremost tooth of the upper escapement-spring, disengages from said tooth, permitting the side-switch to pass into third position. It is then that 5 the side-switch-wipers leave the contact-points 176, 177, 178 and 179 and pass onto the contact-points 180, 181, 182 and 183. The shifting of the side-switch and the disengagement of the side-switch-wiper 166 10 from the contact-point 176 occur just before the interrupter-springs 142 and 143 re-engage, and therefore the circuit through the rotary-magnet is permanently broken in order that no further rotation of the shaft 15 may take place during its operation. At the same time the engagement of the wiper 167 with contact-point 181 provides the private-wiper 80 with guarding potential to protect the trunk seized by the line-wipers 20 78 and 79. Of course, it will be clear that when the wipers 168 and 169 arrive on the side-switch contact-points 182 and 183 the line-conductors 321 and 327 are extended to the connector C over the conductors 334 and 25 335.

It may be stated at this point that if after the subscriber has begun to call, and before the first-selector has trunked to the connector, he should desire to discontinue his call 30 he may interrupt the operation of the first-selector and restore it by simply hanging his receiver on the switch-hook. This may occur while the side-switch is in the first or second position, it matters not. As a result 35 of restoring the receiver both sides of the main line are grounded for a moment. If this occurs while the side-switch is in first position the vertical and rotary line-relays 93 and 94 are magnetized at the same time 40 over circuits that are already known, and as a result the release-magnet 122 of the first-selector is energized and deenergized and the first-selector is restored. It has been described that in its action the release-cam- 45 arm 4, as it passes down when the receiver is restored, flexes the release-springs 38, 37 and 36 into contact for a moment. Of these springs the release-springs 38 and 37, respectively, are connected with the vertical 50 and rotary line-conductors 321 and 327, while the third release-spring 36 is connected to ground G¹. Therefore, as a result, the temporary engagement of these three springs sends a ground impulse over each 55 side of the main line with the usual effect upon the first-selector line-relays 93 and 94. The current through the vertical-line-relay, during its energization, passes from ground G¹, through the springs 21 and 20, conductor 60 318, springs 35 and 34, conductor 319, release-springs 36, 37 and 38, contact-point 45, and spring 42 to the vertical-line-conductor 321, thence through the vertical-line-relay 93 to battery B and to ground G. Through 65 the rotary-line-relay 94, the current also

flows from ground G¹ to the release-spring 36, passing thence to the spring 37, contact-point 44, spring 43, and to the rotary-line-conductor 327, switch-shaft-springs 92 and 91, side-switch-wiper 169, conductor 329, 70 conductor 327, switch-shaft-springs 92 and 91, side-switch-wiper 169, conductor 329, thence through the rotary-line-relay 94 to the non-grounded terminal of the battery B and to ground G. The rotary-line-relay being energized the private-magnet is energized also and, while thus energized, maintains the private-springs 152 and 153 in contact. The vertical-line-relay being energized, and the line-relay springs 97 and 99 being forced together at a time when the private-springs 153 and 152 are in contact, a 80 combination of circuits provides a magnetizing circuit for the release-magnet 122 as follows: from ground G² through the line-relay-springs 99 and 97, conductor 325, private-springs 152 and 153, conductors 341 85 and 342, release magnet 122 to the battery-lead 324, and through battery B to ground G. As a result, the release-magnet attracts its armature 121, and the release-link catches the double-dog-lug 180; then as the release-cam-arm 4 on the switch-hook 3 clears the lug 39 on the release-spring 38, the three release-springs 36, 37 and 38 necessarily fall apart, at which instant the ground connections to the main line-conductors are destroyed and the line-relays 93 and 94 of the first-selector are deenergized. Upon this deenergization there follows also the deenergization of the private-magnet 146 and of the release-magnet 122. As already pointed 90 out, when the release-magnet becomes energized and deenergized the first-selector is released by the release-armature retracting-spring, which latter restores the double-dog 95 123, and retracts the dogs 127 and 128, at which instant the switch-shaft is restored. It will be understood that if the release occurs, however, while the rotation of the switch-shaft is taking place the vertical and 100 rotary line-conductors will be grounded as before; but the side-switch-wipers 168 and 169 being in second position and in contact with the contact-points 178 and 179, respectively, the vertical-line-conductor is then 105 open and the grounding of said conductor at this time produces no effect. But the rotary-line-conductor, however, being connected with the vertical-line-relay 93 by way of the springs 92 and 91, contact-point 179, conductor 343, contact-point 174 and conductor 322, it follows that the grounding of the rotary-line-conductor magnetizes said vertical-relay. Now, since the private-magnet, while the private-wiper is passing over 110 grounded contacts, is retained magnetized, the private-springs 152 and 153 are maintained in contact. Therefore, the grounding of the rotary-line-conductor while the side-switch is in second position produces a 115 magnetization of the vertical-line-relay, 120 conductor 327, switch-shaft-springs 92 and 91, side-switch-wiper 169, conductor 329, conductor 327, 125 and the vertical-line-relay 93.

while the said private-springs are together, and, as a result already pointed out, the magnetization of the release-magnet 122 follows. But as soon as the release-springs 36, 5 37 and 38 at sub-station disengage the ground-circuits to the line are destroyed, the release-magnet is deenergized and the switch is released the same as usual. The shaft, now deprived of the lock furnished by the 10 rotary-locking-dog 128, is rotated back toward normal rotary position upon the end of the shaft-rest 87, and at the instant that the normal-post-arm 88 strikes the normal-post 89 the said shaft-rest enters the longitudinal slot 86, at which time the shaft, losing its only support, falls to normal position, leaving the switch completely restored. Of course, it will be plain that the magnetizing current through the release-magnet in 15 this last case passes, as before, from ground G through the springs 99 and 97 and to the private-spring 152, thence through the private-spring 153 to the release-magnet 122 and through battery B to ground G. Therefore, the releasing of the first-selector while the side-switch is in first position results from energizing both the vertical and rotary line-relays simultaneously.

The release during rotation of the shaft 20 and, therefore, while the side-switch is in second position results from the grounding of the rotary line-conductor and the energizing thereby of the vertical-line-relay while the private-springs 152 and 153 are in 25 contact; but after the first-selector has selected the trunk and the side-switch is in third position, since none of the line-relays remain in connection with either of the side-switch-wipers 168 or 169, and as there is no 30 connection between the adjoining contact-points 182, 178 and 174, and 183, 179 and 175 over which said side-switch-wipers slide, the release is then produced in another manner by means of the so-called back-release-relay 35 105 over what is known as a trunk-release-conductor, as will be pointed out. After the calling line-conductors are extended to the connector the operation of the calling device for the second digit causes the vertical-line-conductor 321 to be grounded three times 40 when the vertical-button 40 is pressed three times. In this way the vertical-line-relay 271 of the connector is energized three times. A current then flows from ground G¹ at the 45 calling sub-station to the ground-post 46, through the spring 42, vertical-line-conductor 321, side-switch-wiper 168, contact-point 182, conductor 344, vertical-private-normal-relay 186, conductor 345, 50 vertical-line-wiper 78, vertical-trunk-conductor 334, vertical-line-relay 271, conductor 346, winding 292 of the differential-relay 290 to the battery-lead 324 and through battery B to ground G. The vertical-line- 55 relay then attracts its armature, and the latter presses the line-relay-springs 273 and 274 into contact, thereby establishing a circuit through the vertical-magnet 213. Through the said vertical-magnet the energizing current passes from ground G¹ 60 through the line-relay-springs 274 and 273, conductor 349, private-springs 244 and 243, conductor 350, side-switch-wiper 255, contact-point 259, conductor 351, and vertical-magnet 213 to the battery-lead 324 and 65 through battery B to ground G. The vertical-magnet on attracting its armature three times raises the shaft 200 three steps and brings the wipers 201, 202 and 203 opposite the first contacts of the third levels of their 70 respective banks. The subscriber again presses the rotary-button 40 once and grounds the rotary-line-conductor 327 once, at which time the rotary-line-relay 277 of the connector is energized. The current in 75 this last circuit passes from ground G¹ to the ground-post 46, through the spring 43 and rotary-line-conductor 327, first-selector switch-shaft-springs 92 and 91, conductor 328, side-switch-wiper 169, contact-point 80 183, conductor 352, rotary-private-normal-relay 187, conductor 353, rotary-wiper 79, rotary-trunk-conductor 335, rotary-line-relay 277, conductor 354, winding 291 of the differential-relay 290, conductor 355, ringer-relay-springs 288 and 289, conductor 356, pole-changing relay-springs 293 and 297, 85 thence through battery B to ground G. As the line-relay 277 is energized the line-relay-springs 279 and 274 are brought together 90 and the private-magnet 234 is energized by current flowing from the ground G¹ through the said springs 274 and 279, conductor 357, private-magnet 234, conductor 358, pole-changing relay-springs 293 and 297 to the 95 battery-lead 324 and through battery B to ground G. When the armature 235 of the private magnet 234 falls back, it permits the connector-side-switch to pass to second position, the side-switch-wiper 255 passing from the 100 contact-point 259 onto the contact-point 260, and the side-switch-wiper 256 from the contact-point 262 onto the contact point 263. The shifting of the side-switch-wiper 255 produces a change in the circuits of the connector whereby, when the vertical-button 40 again is pressed ten times for the last digit, the rotary-magnet 230 instead of the vertical-magnet is operated when the line-relay-springs 273 and 274 are brought into contact. 105 Each time the said springs close a current is sent from ground G¹ through the said springs 274 and 273 and the private-springs 244 and 243 to the side-switch-wiper 255, through the contact-point 260, conductor 359, rotary-magnet 230 to the battery-lead 324, and through battery B to ground G. At each pulsation the rotary-magnet attracts 110 its armature 231, rotating the shaft 200 one step at a time and sliding the wipers 201, 115 120 125 130

202 and 203 along the third level of the banks which they engage. Then for the last time the rotary-button 41 is pressed once. As a result, the rotary-line-conductor 327 is 5 again grounded, and again the rotary-line-relay 277 of the connector is energized once. The said relay in turn causes the private-magnet 234 to become energized and to thus permit the side-switch to pass to third position with the wipers 255, 256, 257 and 258, respectively, in contact with contact-points 261, 264, 267 and 270. The closure of connection between the side-switch-wipers 257 and 258 and contact-points 267 and 270, respectively, connects the calling subscriber's extended line-conductors 334 and 335, through the condensers 304 and 305, with the vertical and rotary line-wipers 201 and 202, respectively, and, therefore, with the normal-conductors 361 and 362 that constitute the terminals of the called line.

The engagement of the side-switch-wiper 256 with the contact-point 264 places a guarding potential at the private-wiper 203 25 at the tenth private-contact of the third level of the private-bank 360, and at all other private-contacts in multiple, to preclude any other connector from cutting in upon the called line #130. The establishment 30 of this guarding potential over the called line not only protects it from further seizure but also forces a current through the bridge-cut-off-relay 310 of the first-selector of the called line, that the latter, through its 35 armature, may separate the bridge-cut-off relay-springs 315, 316 and 317, for reasons already stated. The energizing circuit through the said bridge-cut-off-relay extends from ground G^e to the contact-point 40 264, through the side-switch-wiper 256, conductors 363 and 364, private-wiper 203, private-normal conductor 365, rotary-private-normal-relay-springs 308 and 309, conductor 366, side-switch-wiper 367, conductor 368, 45 bridge-cut-off-relay 310, through battery B and to ground G. It will be noticed that each time that the vertical or rotary line-relay has been energized the energization has occurred in series with one of the windings 50 of the differential-relay 290. The energizing of said differential-relay hitherto has played no part in the operation. It will be shown, however, at a proper time that the energization of the differential-relay is essential 55 to certain hereinafter described operations. Not only has it been shown that the vertical-line-relay is energized in series with one of the windings of the differential-relay, but also in series with the vertical-private-normal-relay 186 of the first-selector; and the rotary-line-relay also in series 60 with the rotary-private-normal-relay 187 of the same selector; but neither of these relays up to the present time has played any part 65 of significance. Their utility will be set

forth in the following description. Connection between the calling and called lines having been established the calling subscriber is in a position to signal the called line by pressing his signaling-button 15. 70 But before going further it may be explained that if for any reason the called line is busy at the time that the calling subscriber grounds the rotary-line-conductor 327 for the last time, as explained in the 75 matter immediately preceding, to transfer the connector-side-switch from second to third position and to complete the connection, the connector is released. For instance, if the line #130 has been called by 80 any connector there will be a guarding potential at the tenth private-contact of the third level of the private-bank 360 corresponding to the line of the sub-station #130. Or, on the other hand, if the first-selector 85 A¹ of the called line is being used, the same private-bank-contact will be connected to ground from the instant that the side-switch passes to third position and the side-switch-wiper 367 finds the grounded contact-point 90 369. Said guarding potential will reach the private-bank of the connector by way of the private-normal-conductor 365. At any rate, if the private-wiper 203 finds a guarding potential at the tenth contact of the third level 95 of the private-bank 360 at the instant that the calling subscriber grounds his rotary-line-conductor 327 for the last time, then instead of the side-switch being tripped into third position the connector will be released, 100 because the private-magnet 234 on becoming energized as a final result of grounding the rotary-line-conductor 327 completes an energizing circuit through the release-magnet 105 of the connector when the armature of the 110 said private-magnet forces the springs 245 and 246 into contact. The energizing circuit for the release-magnet extends from the grounded terminal of the battery B to the tenth contact of the third level of the connector-private-bank 360, through the private-wiper 203 to the conductor 364, side-switch-wiper 256, contact-point 263, conductor 370, private-springs 245 and 246, conductors 371 and 372, release-magnet 218, 115 conductors 373 and 374, through the differential-relay-springs 301 and 302, to the battery-lead 324, thence through battery B to ground G. Since this occurs while current 120 is flowing through the differential-relay-winding 291, in series with the rotary-line-relay 277, the differential-relay 290 is thereby energized; therefore, the springs 301 and 302, through which the releasing circuit extends, are maintained in contact. The connector-release-magnet being energized, the release-armature then moves the double-dog so that the lug 227 is caught and held in the aperture 228 on the end of the release-link 222. Of course, when the double-dog 221 is 125

thus rotated the locking-dog 225 is withdrawn from the longitudinal teeth 205. The shaft is then free to rotate back to its normal rotary position because of the tension 5 in the coiled spring 208, which rotation ceases only when the normal-post-arm 207 strikes the normal-post 375. At that instant the shaft-support 210 enters the slot 209 and the said shaft of necessity falls to 10 its normal position.

The release-armature, when it rotates the double-dog 221, at the same time swings the side-switch to its first position, about the pivots 252 of the latter, by means of the 15 link 254 and the release-arm 226. The latter, by pressing the former back, forces the escapement-finger 248 back between the escapement-springs 236 and 237, where it is then caught behind the rearmost lower tooth 20 where it remains until the connector 25 comes into use again. The restoration of the connector-shaft begins even while the release-magnet is in an energized state; but since the energizing circuit through said 25 magnet comprises the private-wiper 203 and the side-switch-wiper 256, it is evident that when the shaft rotates back toward normal position, and when the side-switch-wiper 256 is forced away from the contact-point 30 264, the energizing circuit will then be destroyed at two points, at which time the connector-release-armature 219 regains its normal position. The calling subscriber, thinking he has established connection, 35 presses the button 15 to ring or signal the called subscriber, with the result that the vertical-line-conductor is grounded. This produces, of course, an energization of the connector-vertical-line-relay 271 in the usual 40 manner; and since the connector-side-switch is in first position the latter relay produces in turn the energization of the connector- 45 vertical-magnet 218, through a circuit that is already familiar when the line-relay- 50 springs 273 and 274 are pressed into contact. When the signaling-button is pressed the ground connection to the vertical-line-conductor 55 321 is not established through the ground-post 46, but through the following 60 circuit: from ground G¹ through the substation relay-springs 21 and 20, conductor 318, signaling-button-springs 18 and 16, primary circuit-springs 26 and 27, contact-point 45 and spring 42 to the vertical-line- 65 conductor. As a result, and by means previously described, the shaft of the connector is raised and the springs 211 and 212, which it controls by the normal-post-arm 207, are brought into contact. Upon the engagement 70 of these two springs 211 and 212 a circuit is completed through which a busy-signal current is transmitted to the receiver of the calling subscriber, which current may originate 75 in any suitable apparatus commonly used in telephone exchanges and comprising

a coil 376 in which the said busy-signal current is induced. The path of the current may be traced from the coil 376 to the conductor 377, springs 212 and 211, conductor 378, contact-point 268, side-switch-wiper 258, ringer-relay-springs 283 and 282, conductor 379, condenser 305, trunk-conductor 333, rotary-line-wiper 79, conductor 353, rotary-private-normal-relay 187, conductor 352, contact-point 183, side-switch-wiper 169, first-selector switch-shaft-springs 91 and 92, rotary-line-conductor 327, spring 43, contact-point 44, conductor 380, sub-station relay-springs 23 and 22, conductor 381, springs 31 and 30, transmitter 8, primary coil 11, signaling-button-springs 17 and 16, primary circuit-springs 26 and 27, contact-point 45, spring 42, vertical-line-conductor 321, side-switch-wiper 168, contact-point 182, conductor 344, vertical-private-normal-relay 186, conductor 345, vertical-line-wiper 78, vertical-trunk-conductor 334, vertical-line-relay 271, conductor 346, winding 292 of the differential-relay 290, battery-lead 324 and back to the coil 376. The calling subscriber, learning that the desired line is busy, will then restore his receiver to its switch-hook, thereby grounding again, in a familiar manner, the vertical and rotary line-conductors 321 and 327. Grounding the former at the sub-station energizes, as usual, the vertical-line-relay 271 of the connector and the differential-relay 290. Grounding the latter at the sub-station energizes the rotary-line-relay 277 of the connector and reinforces or augments, in this case, the already energized differential-relay 290. The two line-relays 271 and 277 being energized simultaneously, and the differential-relay 290 being energized as well, so that the differential-relay-springs 301 and 302 are forced into contact while the trunk-release-springs 275 and 276 are maintained connected, the release-magnet 218 is magnetized in series with the back-release-relay 105 of the first-selector A. This energizing circuit 100 extends from the ground terminal G¹ at the first-selector side-switch-contact-point 181, side-switch-wiper 167, conductor 336, back-release-relay 105, conductor 337, private-wiper 80, private-bank-conductor 382, trunk-release-springs 275 and 276, conductors 383 and 372, release-magnet 218, conductors 373 and 374, and through the differential-relay-springs 301 and 302 to the battery-lead 324, 110 and through battery B to ground G. 115

Of course, simultaneously with the energizing of the connector-release-magnet, the first-selector back-release-relay 105 is also magnetized, and the latter by attracting its 120 armature 106 causes the back-release-relay-springs 107 and 108 to engage in contact. An energizing circuit is thereby established through the first-selector release-magnet 122, in which the current passes from ground G¹ 130

through the back-release-relay-springs 107 and 108, to the conductors 384 and 342, thence through the release-magnet 122 to the battery-lead 324, and through battery B and 5 to ground G. The release-magnet of the connector being energized the release-armature 219 is attracted and, as before, the double-dog is rotated or swung to its normal position away from the connector-shaft 10 which then falls to its normal position, separating at the same time the busy circuit shaft-springs 211 and 212. The first-selector release-magnet being energized the first-selector release-armature 121 is attracted 15 and the release-springs at the sub-station spring apart as the switch-hook reaches its lowest position. All the release energizing circuits are then destroyed and the first-selector is fully restored in a manner that is 20 already well known; and at the same time the connector-line-relays, as well as the connector-release-armature, regain their normal positions, leaving the latter switch in readiness for further use. But it has been described 25 that the called line is not busy and that the connection with said line is completed. Therefore, when the signaling-button 15 is pressed, in a manner already stated, the subscriber grounds the vertical-line-con- 30 ductor 321, as above, and the vertical-line-relay, through circuits already described, is energized. Since the side-switch of the connector is in third position, and the connector-side-switch-wiper 255 is in engage- 35 ment with the contact-point 261, the engagement of the line-relay-springs 273 and 274, at the energization of the vertical-line-relay, produces in turn an energization of the ringer-relay 280. The energizing 40 current passes from ground G* through the said line-relay-springs 274 and 273, private-springs 244 and 243, conductor 350, side-switch-wiper 255, contact-point 261, ringer-relay 280, conductors 383 and 374, 45 springs 301 and 302, to the battery-lead 324 and through battery B to ground G. The ringer-relay-armature 281 then forces the ringer-relay-springs 283 and 286 away from the springs 282 and 285 and onto the 50 springs 284 and 287, at the same time separating the springs 288 and 289. A signaling or ringing current then passes onto the called subscriber's line as follows: from the ringer-generator J to the brush 386, and 55 thence over the conductor 387, through the ringer-relay-springs 284 and 283, side-switch-wiper 258, contact-point 270, conductor 388, rotary-line-wiper 202, rotary-normal-con- 60 ductor 362 of the connector-line-bank 389, rotary-line-conductor 390, spring 391, contact-point 392, conductor 393, ringer 394, condenser 395, ringer-circuit-spring 396, switch-hook 397, conductor 398, contact-point 399 and spring 400, vertical-line-con- 65 ductor 401, vertical-normal-conductor 361,

vertical-line-wiper 201, conductor 402, contact-point 267, side-switch-wiper 257, ringer-relay-springs 286 and 287 and conductor 403, back to the brush 404 and to the generator J. The particular generator J, allotted to the connector C, produces a current of such frequency that only the bells 394 at the said sub-station will respond. If the sub-station #230 had been called, a different connector 70 would have been reached by the action of the first-selector A, which connector would have been one of a group provided with a ringer-generator giving current of a particular frequency capable only of ringing stations provided with ringers that respond to currents produced by said generator. Of course, any suitable signaling system may be employed. Although the current sent over the line to the sub-station #130 passes also through the ringing apparatus of the sub-station #230, 80 no signal is given at the latter station, since the bells are so adjusted that they do not respond to the current of the character used to signal the sub-station #130. As soon as the calling subscriber ceases to press the signaling-button 15 the ringer-relay becomes deenergized and the springs 283 and 286, respectively, reengage with the springs 282 and 285, at which instant the calling and 85 called lines are again restored in connection. 90 The ringer or bell at the called sub-station having sounded the subscriber answers by removing the receiver 405 from his switch-hook 397. The said receiver is then connected inductively with the receiver 2 at the 100 calling sub-station over circuits that will be explained.

When the called subscriber permits his switch-hook to rise, the primary circuit-springs 406 and 407 then come into contact, 105 as well as the springs 408, 409 and 410. At once a flow of current is established through the transmitter 411, which passes from ground G* at the connector-side-switch-contact-point 264, side-switch-wiper 256, conductors 363 and 412, differential-relay-springs 299 and 300, conductor 413, pole-changing-relay 295, to the conductor 379, ringer-relay-springs 282 and 283, side- 110 switch-wiper 258, contact-point 270, conductor 388, rotary-line-wiper 202, rotary-normal-conductor 362, rotary-line-conductor 390, spring 391, contact-point 392, conductor 393, sub-station relay-springs 414 and 415, conductor 416, springs 409 and 408, transmitter 411, primary winding 417 of the induction-coil 418, contact-point 419, spring 420, conductor 421, springs 406 and 407, conductor 398, contact-point 399, spring 400, to the vertical-line-conductor 401, thence to the 115 vertical-normal-conductor 361, vertical-line-wiper 201, conductor 402, contact-point 267, side-switch-wiper 257, ringer-relay-springs 286 and 285, conductor 422, and through the retardation-coil 303 to the battery-lead 324, 120 125 130

and through battery B to ground G. Included in this circuit is the pole-changing-relay 295, which becomes energized, attracting, at once, its armature 294, the latter 5 forcing the pole-changing-relay-spring 293 from engagement with the spring 297 and into engagement instead with the spring 296. As soon as the said springs (the springs 293 and 296) close together the transmitter 8 at 10 the sub-station #320 is provided with current for talking purposes. This circuit extends from ground G^a at the connector-side-switch-contact-point 264, through side-switch-wiper 256, conductors 363 and 412, 15 pole-changing-relay-springs 296 and 293, conductor 356, ringer-relay-springs 289 and 288, conductor 355, differential-relay-winding 291, conductor 354, rotary-line-relay 277, trunk-conductor 335, rotary-line-wiper 79, conductor 353, rotary-private-normal-relay 187, conductor 352, contact-point 183, side-switch-wiper 169, conductor 328, springs 91 and 92, rotary-line-conductor 327, spring 43, contact-point 44, conductor 380, sub-station 25 relay-springs 23 and 22, conductor 381, springs 31 and 30, transmitter 8, primary winding 11 of the induction-coil 10, contact-point 17, spring 16, primary circuit-springs 26 and 27, contact-point 45, spring 42, vertical-line-conductor 321, side-switch-wiper 168, contact-point 182, conductor 344, vertical-private-normal-relay 186, conductor 345, vertical-line-wiper 78, vertical-trunk-conductor 334, vertical-line-relay 271, conductor 346, winding 292 of the differential-relay 290, to the battery-lead 324 and through battery B to ground G. Although the above energizing circuit includes the vertical and rotary line-relays 271 and 277 of the connector 40 so that said relays are energized, and although, therefore, the trunk-release-springs 275 and 276 are maintained in contact, the release-magnet 218 of the connector does not become energized because the differential-relay 45 is not energized and because, therefore, the differential-relay-springs 301 and 302 are kept apart. It is true that the same current that passes through the said line-relays also passes through the windings 291 and 292 of the differential-relay 290; but, as has been pointed out, when the current passes through said two differential-relay windings 291 and 292, in the direction that it does under the present conditions, the 50 two windings then neutralize or counteract each other, rendering the said relay inactive. Not only are the vertical and rotary line-relays 271 and 277 of the connector maintained energized while the pole-changing-relay 295 55 is energized, but the vertical and rotary private-normal-relays of the first-selector are energized as well. When the first-selector side-switch passes to third position and the side-switch-wiper 167 engages the grounded 60 contact-point 181, a guarding potential is

established at the private banks of the connectors of the group in which the normal-conductors 423 and 424 of the line of the sub-station #120 terminate. This guarding potential is extended to the said connector-private-banks over the private-normal-conductor 339; or when the private-normal-relays 186 and 187 are deenergized, then such guarding potential is established through the private-normal-relay-springs 191 and 190 instead. The transmitters 8 and 411 of the calling and called sub-stations being energized, as well as the primary windings 11 and 417 of the induction-coils 10 and 418, and the receivers at the respective sub-stations being connected in series with the secondary windings associated with the corresponding primary windings 11 and 417, it follows that the subscribers are then in a position to speak to each other.

The circuit over which the voice-currents pass from one sub-station to the other is as follows: Beginning with the transmitter 411 at the called sub-station it extends through the primary winding 417, contact-point 419, spring 420, conductor 421, springs 406 and 407, conductor 398, contact-point 399, spring 400, vertical-line-conductor 401, vertical-normal-conductor 361, vertical-line-wiper 201, conductor 402, contact-point 267, side-switch-wiper 257, ringer-relay-springs 286 and 285, conductor 422, condenser 304, trunk-conductor 334, vertical-line-wiper 78, conductor 345, vertical-private-normal-relay 186, conductor 344, contact-point 182, side-switch-wiper 168, vertical-line-conductor 321, spring 42, contact-point 45, primary 105 springs 27 and 26, spring 16, contact-point 17, primary winding 11 of the induction-coil 10, transmitter 8, springs 30 and 31, conductor 381, sub-station relay-springs 22 and 23, conductor 380, contact-point 44, spring 43, rotary-line-conductor 327, contact-point 92, spring 91, conductor 328, side-switch-wiper 169, contact-point 183, conductor 352, rotary-private-normal-relay 187, conductor 353, rotary-line-wiper 79, rotary-trunk-conductor 335, condenser 305, conductor 379, ringer-relay-springs 282 and 283, side-switch-wiper 258, contact-point 270, conductor 388, rotary-line-wiper 202, rotary-normal-conductor 362, rotary-line-conductor 390, spring 391, contact-point 392, conductor 393, sub-station relay-springs 414 and 415, conductor 416, springs 409 and 408, and again to the transmitter 411. While this connection is established the non-interfering characteristics of my system come into use if the subscriber at sub-station #230 attempts to make a call. It should be evident that if while the sub-stations #320 and #130 are connected the subscriber at the sub- 130

station #230 should try to call, and thereby ground either or both of the line-conductors 390 and 401, he then will interfere with the conversation that is taking place between the connected sub-stations, since grounding the vertical-line-conductor 401 would short-circuit the pole-changing-relay 295, the transmitter 411, and the primary winding 417 of the induction-coil 418. The short-circuit 5 would, of course, extend from the ground G^s to the vertical-line-conductor 401, by whatever path the ground connection may be made at the interfering station. Clearly short-circuiting or shunting the pole-changing-relay 295 would cause said relay to be deenergized, of course, with the result that talking current for the calling subscriber is cut off. The effect of short-circuiting the transmitter 411 is obvious. It 10 is for the purpose of preventing such interference that I have provided each sub-station with a non-interfering device like the one described at sub-station #320, comprising the line-relay-magnet 19 and the relay-springs 20, 21, 22 and 23. The connection described being established, should the subscriber at the sub-station #230 then remove his receiver 425 from its hook 426 the sub-station relay 427 at said sub-station will be 15 energized and its armature 428 locked to prevent a connection between the ground-post 429, the signaling-button-contact 430, or the ground-release-spring 431 and the ground G^s. The switch-hook-springs 432 and 433, and 434 and 435 under the control 20 of the cam-arms 437 and 436, respectively, are so adjusted that the springs 432 and 433, which are normally disengaged as indicated at sub-station #220, are thrown into contact 25 as the switch-hook rises, after the subscriber removes his receiver, and before the spring 434 is separated from the spring 435. At that time there is a flow of current through the sub-station relay 427 from the sub-station 30 ground G^s through the conductor 438, springs 435 and 434, conductor 439, springs 432 and 433, sub-station relay 427, conductor 440, contact-point 441, spring 442, rotary-line-conductor 390, spring 391, contact-point 392, 35 conductor 393, sub-station relay-springs 414 and 415, conductor 416, springs 409 and 408, transmitter 411, primary winding 417 of the induction-coil 418, contact-point 419, spring 420, conductor 421, springs 406 and 407, conductor 398, contact-point 399, spring 400, vertical-line-conductor 401, vertical-normal-conductor 361, vertical-line-wiper 201, conductor 402, contact-point 267, side-switch-wiper 257, ringer-relay-springs 286 40 and 285, conductor 422, retardation-coil 303 to the battery-lead 324, and through battery B to ground G. It will be noticed, therefore, that at the instant that the said sub-station relay 427 becomes energized the transmitter 411 receives current through two 45 and 285, conductor 422, retardation-coil 303 to the battery-lead 324, and through battery B to ground G. It will be noticed, therefore, that at the instant that the said sub-station relay 427 becomes energized the transmitter 411 receives current through two 50 and 285, conductor 422, retardation-coil 303 to the battery-lead 324, and through battery B to ground G. It will be noticed, therefore, that at the instant that the said sub-station relay 427 becomes energized the transmitter 411 receives current through two 55 and 285, conductor 422, retardation-coil 303 to the battery-lead 324, and through battery B to ground G. It will be noticed, therefore, that at the instant that the said sub-station relay 427 becomes energized the transmitter 411 receives current through two 60 and 285, conductor 422, retardation-coil 303 to the battery-lead 324, and through battery B to ground G. It will be noticed, therefore, that at the instant that the said sub-station relay 427 becomes energized the transmitter 411 receives current through two 65 and 285, conductor 422, retardation-coil 303 to the battery-lead 324, and through battery B to ground G. It will be noticed, therefore, that at the instant that the said sub-station relay 427 becomes energized the transmitter 411 receives current through two

multiple circuits, one comprising the pole-changing-relay 295 at the connector, and the other the sub-station relay 427, said circuits being grounded at G^e and G^s , respectively.

Another point should be noticed, namely 70
that the releasing rod 443 that has supervision
over the locking member 444 of the sub-
station relay 427 is so adjusted that when the
switch-hook rises to the point at which the
said sub-station relay is magnetized the said
rod has risen sufficiently to permit the said
locking member 444 to operate. As soon as
the relay 427 is magnetized the armature
428 is attracted by the pole-piece of said relay,
which armature, as it strikes the pole-
piece, clears or disengages the locking member 444. The latter is forced upward in
front of said armature to such a position
that the armature is locked against the pole-
piece and retained there even after the ener- 85
gizing circuit is broken when the switch-
hook passes still farther upon its stroke.
The said armature 428, being depressed,
causes the spring 445 to be separated from
the spring 446, thereby interrupting the con- 90
tinuity of the ground connection between
the ground-post 429, the ground-contact-
point 430, and the release-spring 431 to the
ground terminal G^s, even after the ground- 95
circuit-springs 447 and 448 are permitted to
close. After this has been accomplished the
subscriber at the sub-station #230 may work
his calling device, press his signaling-but- 100
ton, or hang up his receiver without inter-
fering with the subscribers that are talking
at the time. Since the sub-station #230 is
connected in multiple with the sub-station
#130, the transmitter 449 is, therefore, ener- 105
gized in series with the sub-station relay 427
when the switch-hook-springs 434 and 435
separate and when the springs 450, 451 and 110
434 are brought into contact instead. The
current passes from the ground G^s to the
rotary-line-conductor 390, through the coil
427, springs 433 and 432, and springs 434, 115
451 and 450, transmitter 449, primary wind-
ing 453 to the vertical-line-conductor 401,
and to the non-grounded terminal of bat-
tery B. It might appear that no voice-cur- 120
rents will pass to and from the line through
the talking apparatus at station #230; but
since the said sub-station relay 427 is bridged
by the condenser 452 the voice-currents find
no trouble in passing. The object in this 125
construction is to enable the subscriber at
the interfering station to discover the fact
that the line is busy at the time and to speak
if he desires. Said voice-currents pass from
the vertical-line-conductor 401, through the
spring 455, contact-point 456, conductor 457,
springs 458 and 459, conductor 460, spring 130
461, contact-point 462, primary winding 453
of the induction-coil 454, transmitter 449,
springs 450, 451 and 434, conductor 439,
springs 432 and 433, conductor 463, con- 135

denser 452, conductor 440, contact-point 441, and spring 442 to the rotary-line-conductor 390. Similarly, if the subscriber at the sub-station #220 should attempt to make a call 5 while the sub-stations #320 and #130 are connected the sub-station relay 464 at said sub-station #220 will be energized to accomplish the same object described in connection with the sub-station #230. The energizing 10 circuit through the said relay at the time when the switch-hook-springs 465 and 466, as well as the springs 467 and 468, are in contact is completed over a circuit from ground G through the conductor 469, springs 15 466 and 465, springs 468 and 467, conductor 470, sub-station relay 464, conductor 471, contact-point 472, spring 473, rotary-line-conductor 327, spring 43 of the sub-station #320, contact-point 44, conductor 380, re- 20 lay springs 23 and 22, conductor 381, switch-hook-springs 31 and 30, transmitter 8, primary winding 11 of the induction-coil 10, contact-point 17, spring 16, primary circuit-springs 26 and 27, contact-point 45, spring 25 42, vertical-line-conductor 321, side-switch-wiper 168, contact-point 182, vertical-private-normal-relay 186, vertical-line-wiper 78, vertical-trunk-conductor 334, connector-vertical-line-relay 271, conductor 346, winding 30 292 of the differential-relay 290 to the battery-lead 324, and through battery B to ground G. The sub-station relay 464 being thus energized and locked, it follows that the ground connection from the ground-post 35 474, the signaling ground contact-point 475, and the release-spring 476, to the ground terminal G is destroyed or opened in the same manner described in connection with sub-station #230. Therefore, the subscriber 40 at sub-station #220 will, by working his calling device, pressing his button, or hanging up his receiver, not interfere with the connections already established. As will be described, by the simultaneous grounding of 45 both the line-conductors of the calling line, when a connection between two lines exists, all the switches are released; and even if this occurs while a subscriber is in the process of establishing a connection, the switches are 50 released also. In order to prevent such releasing of the switches by a second subscriber on the same line, after a first subscriber has begun to use the line, the sub-stations are provided with circuits and means, such as 55 described in connection with the sub-station #230.

It will be noticed that when the switch-hook is up the vertical and rotary line-conductors are connected together through the 60 transmitter 8. For example, the line-conductors 321 and 327, when the switch-hook 3 of the sub-station #320 is raised, are connected through the spring 42, contact-point 45, springs 27 and 26, signaling-button-spring 65 16, contact-point 17, primary winding 11, transmitter 8, springs 30 and 31, conductor 381, sub-station relay-springs 22 and 23, conductor 380, contact-point 44 and spring 43. Therefore, grounding either one of the line-conductors, as far as the switching apparatus at the central station is concerned, grounds both with the result that the switches are released. However, when all the switch-hooks are down, and while the ringer apparatus at each station is bridged 70 across the line, the line-conductors are not connected to permit direct currents to pass from one to the other, since each ringer has a condenser connected therewith in series. In the sub-station #220, for instance, when 80 the switch-hook is down the circuit between the vertical and rotary line-conductors 321 and 327 through the ringer 477 comprises a condenser 478 in series, and since there is no other connecting circuit between said 85 line-conductors the first subscriber who comes on the line may perform his call successfully. It should be noted that the sub-station relay 464 of the sub-station #220 may be energized when the hook is raised 90 not only after the connection between the sub-stations #320 and #130 is completed, but also at any time after the switch-hook of any other station on the same line with said sub-station #220 has been raised. For instance, after the switch-hook 3 at the sub-station #320 is raised, and even before the switches at the central office have been operated, the energizing circuit for the relay 464 extends from ground G through the springs 100 466 and 465, springs 468 and 467, relay 464, rotary-line-conductor 327, spring 43 at the sub-station #320, contact-point 44, conductor 380, sub-station relay-springs 23 and 22, conductor 381, springs 30 and 31, transmitter 105 8, primary winding 11, contact-point 17, spring 16 and springs 26 and 27, contact-point 45 and spring 42, vertical-line-conductor 321, side-switch-wiper 168, contact-point 174, vertical-line-relay 93 to the battery-lead 324, and through battery B to ground G. The said relay may also be energized 110 when the first-selector-shaft 77 is raised and while the side-switch is in first position. In this case the said relay 464 receives current not only through the circuit just described, but also through a multiple as follows: from the rotary-line-conductor through the switch-shaft-springs 92 and 91, side-switch-wiper 169, contact-point 175, rotary-line-relay 94 to the battery-lead 324 and through battery B to ground G. Again, while the first-selector-shaft is raised and the side-switch is in second position, the energizing circuit then extends from the ground G 115 through the said relay 464 to the rotary-line-conductor 327, thence through the switch-shaft-springs 92 and 91, side-switch-wiper 169, contact-point 179, conductor 343, vertical-line-relay 93, to the battery-lead 324, 120 125 130

and through battery B to ground G. Also, when the first-selector is so operated that the shaft is raised and the side-switch is in third position, and before the called subscriber has answered, the current then passes from ground G^o through said relay to the rotary-line-conductor, through the switch-shaft-springs 92 and 91, side-switch-wiper 169, contact-point 183 and rotary-private-normal-relay 187, rotary-line-wiper 79, conductor 335, connector-rotary-line-relay 277, differential-relay-winding 291, ringer-relay-springs 288 and 289, pole-changing-relay-springs 293 and 297 to the battery-lead 324, and through battery B to ground G. At the same time current flows through a multiple circuit from the rotary-line-conductor 327 through the primary winding of the induction-coil 10 and transmitter 8 of the substation #320 to the vertical-line-conductor 321, thence through the side-switch-wiper 168, vertical-private-normal-relay 186, vertical-line-wiper 78, conductor 334, connector-vertical-line-relay 271, winding 292 of the differential-relay-coil 290 to battery-lead 324 and through battery B to ground G. It will thus be seen that no matter in which position the switches may be, the first subscriber on the line that removes his receiver gains exclusive control of the line until he restores his receiver. What has been said with respect to the substation #320, on the called line, in connection with an energizing circuit through the transmitter 449 and substation relay 427 in series, after the line-relay is locked, is also true of the sub-station #220 of the calling line. Furthermore, the voice-currents between the talking substations will affect the receiver at the locked-out station in the same manner and over the same circuits already described.

It should be evident that once a sub-station is locked out, so to speak, it is necessary that the receiver be restored to the switch-hook before said sub-station may be put in use again. When once the relay-armature 428 shown at sub-station #230, for instance, is locked, then nothing but the downward thrust of the rod 443 will restore the armature 428 and the springs it controls. The conversation between the subscribers at the sub-stations #320 and #130 having terminated, the subscriber at the calling sub-station may then release the connection at any instant by simply restoring his receiver to its hook. By restoring the receiver the subscriber grounds the rotary and vertical line-conductors in a manner that has been pointed out. Since the rotary line is already grounded at the connector-side-switch-contact-point 264, it is obvious that a grounding of said line at the release-spring 36 short-circuits or shunts all relays between the sub-station and the connector-side-switch-wiper 256 that are connected in series in said line. The rotary-private-normal-relay 187, the connector-rotary-line-relay 277 and the winding 291 of the differential-relay 290 are thus affected. The shunted circuit connection extends from ground G^o at the sub-station #320 through the sub-station relay-springs 21 and 20, conductor 318, springs 35 and 34, conductor 319, release-springs 36 and 37, contact-point 44, spring 43 to the rotary-line-conductor 327, thence through the switch-shaft-springs 92 and 91, side-switch-wiper 169, contact-point 183, rotary-private-normal-relay 187, rotary-line-wiper 79, conductor 335, rotary-line-relay 277, winding 291 of the differential-relay 290, ringer-relay-springs 288 and 289, pole-changing-relay-springs 293 and 296 to the side-switch wiper 256, contact-point 264, and to ground G^o. As soon as the said short-circuit is established the energizing current that has been flowing from the ground terminal G^o toward the sub-station #320 is cut off, so that the balance of the differential-relay 290 is disturbed, and the said relay then becomes energized, attracting its armature 298, separating the springs 299 and 300 and bringing the springs 301 and 302 into contact. The energizing current through the winding 292 of the differential-relay 290, that at this point maintains said relay magnetized, passes from ground G^o through the sub-station relay-springs 21 and 20, ground circuit-springs 35 and 34, release-springs 36, 37 and 38, vertical-line-conductor 321, side-switch-wiper 168, contact-point 182, vertical-private-normal-relay 186, vertical-line-wiper 78, connector-vertical-line relay 271, conductor 346, winding 292 of the differential-relay 290 through battery B to ground G. Since the energizing circuit through the pole-changing-relay 295 comprises the differential-relay-springs 300 and 299, it is evident that when said springs are forced apart the said energizing circuit is destroyed; the pole-changing-relay 295 then releases its armature 294, and as a result the pole-changing-relay-spring 293 shifts from engagement with the spring 296 into engagement with the spring 297. As soon as the pole-changing-relay-spring 293 reengages the spring 297, the connector-rotary-line-relay 277 and the winding 291 of the differential-relay 290 become energized by a current that now flows in an exactly opposite direction from the current that maintains said winding 291 and line-relay 277 energized before the release occurs. The energizing current now flows from ground G^o to the release-springs 36 and 37, thence to the rotary-line-conductor 327, through the relays 187 and 277, and the winding 291 of the differential-relay 290, through the ringer-relay-springs 288 and 289, pole-changing-relay-springs 293 and 296.

297, and through battery B to ground G. The winding 291 which originally neutralized the winding 292 now, it will be noticed, since the current through the latter is reversed, reinforces or augments the former.

5 Therefore, the rotary-line-relay 277 is again energized and the trunk-release-spring 276 of the connector, under the control of the said rotary-line-relay 277, is again restored in connection with the trunk-release-spring 275. The result of the electrical engagement of said trunk-release-springs 275 and 276 is, since the differential-relay-springs 301 and 302 are in contact, that the connector-release-magnet 218 in series with the first-selector back-release-relay 105 becomes energized through a circuit as follows: from the ground G' to the first-selector side switch-contact-point 181, side-switch-wiper 167, conductor 336, back-release-relay 105, conductor 337, private-wiper 80, trunk-release-conductor 332, trunk-release-springs 275 and 276, conductors 333 and 372, release-magnet 218, conductors 373 and 374, differential-relay-springs 301 and 302 to the battery-lead 324, and through battery B to ground G. Therefore, both the back-release-relay of the first-selector and the release-magnet 218 of the connector are energized 30 at the same time.

The result of energizing the connector-release-magnet is well known. At the same time the back-release-relay 105 of the first-selector attracts its armature 106 and closes 35 a connection between the back-release-relay-springs 107 and 108 that establishes an energizing circuit through the release-magnet 122 from ground terminal G', through the said back-release-springs 107 and 108, and the release-magnet 122, to the battery-lead 324, thence through battery B to ground G. As a result the first-selector release-magnet attracts its armature which remains thus attracted as long as the line-conductors 321 and 327 are retained grounded. 40 As soon as the connector-side-switch is restored, so that the connector-side-switch-wiper 256 leaves the contact-point 261, the energizing circuit through the bridge-cut-off-relay 310 of the first-selector A' is destroyed or opened, at which instant the bridge-cut-off-relay-springs 315, 316 and 317 resume their normal positions. As soon 45 as the switch-hook descends far enough to permit the release-springs 36, 37 and 38 to spring apart the connection to the line-conductors 327 and 321 is broken and the line-relays 271 and 277 of the connector become deenergized, as well as the differential-relay 290 and the private-normal-relays 187 and 186. The trunk-release-springs 275 and 276 upon separating destroy the energizing circuit through the connector-release-magnet 218 and the first-selector back-release-relay 105, both of which become deenergized, at

which time the first-selector A is restored, together with the connector-release-armature, thus leaving the exchange apparatus in normal position. If the subscriber at the sub-station #130 restores his receiver before 70 the subscriber at the sub-station #320, then as soon as the switch-hook permits the springs 406 and 407 to separate the energizing circuit through the pole-changing-relay 295 is destroyed, which latter then permits 75 the pole-changing-relay-spring 293 to leave the spring 296 and return into engagement with the spring 297. Clearly, then, when the springs 293 and 296 separate, the talking current flowing to the sub-station #320 80 through the transmitter 8 is stopped. At this time the connector-line-relays 277 and 271 retain their normal positions (and also the trunk-release-springs 275 and 276) until after the subscriber at the sub-station #320 85 grounds both of his line-conductors 327 and 321 by restoring his receiver and forcing the release-springs 36, 37 and 38 into contact. The line-relays 271 and 277 of the connector will then become energized simultaneously, 90 in a well-known manner, together with the differential-relay 290, and the connector and the first-selector will be released in the manner described when the subscriber at the sub-station #320 restored his receiver after receiving a busy signal. 95

In my improved system not only may a subscriber on one line call any other subscriber on any line, but he may also, by means of the central office switches, call 100 back on his own line, so to speak, in order to signal and communicate with any other subscriber on his own line. The switches are adapted to perform either operation. The methods and manner by which one subscriber may call another on the same line will be apparent from the following: In Fig. 4 the subscriber at the sub-station #320 is shown calling the subscriber at the sub-station #120, while the sub-station #220 105 is shown locked out from attempting to call after the switch-hook 3 is raised. In the usual manner, when the subscriber at sub-station #320 begins to make a call he removes his receiver from the switch-hook 3, 110 by which act he gets control, as stated, of the line in order that no other subscriber may use the same for calling until he is through. For the same reason and over the same circuits that have already been described the subscriber at sub-station #220 115 is locked out if he raises his receiver after a subscriber at sub-station #320 or any other station on the same line has permitted his switch-hook to rise. However, after a connector has completed a connection with the calling line itself the paths over which the energizing current is furnished to the sub-station relay 464 are then slightly modified, but attention will be called to this later on. 120 125 130

Having removed his receiver the subscriber at the sub-station #320, in order to call the subscriber #120, presses the vertical-button 40 once and the rotary-button 41 once; and 5 again the vertical-button 40 twice and the rotary-button 41 once; and for the last time the vertical-button 40 ten times and the rotary-button 41 once. When the vertical-line-conductor 321 is grounded once for the 10 first time the first-selector-shaft 77 is raised to the first level, and when the rotary-line-conductor 327 is grounded once, immediately after, the usual rotation of the shaft ensues, which, if the first nine trunks of the first 15 level are then busy, will cause the shaft to rotate the line-wipers onto the tenth set of contacts of the first level; then the line-wipers 78 and 79 are in contact with the trunk-conductors 334 and 335, and the private-wiper 20 with the private-trunk-conductor 382, which conductors lead to the connector C. The first-selector having extended the line-conductors 321 and 327 to the connector C, it follows that a grounding of the vertical-line-conductor 321 twice by pressing the button 40 twice produces an energization of the connector-vertical-line-relay 271 over circuits that are well known.

The vertical-line-relay 271 by pressing 30 springs 273 and 274 into contact, in the usual manner, causes the vertical-magnet 213 to be energized twice, the latter raising the connector-shaft 200 two steps, thereby placing the shaft-wipers 201, 202 and 203 on a level 35 with the second level of their respective banks 389 and 360. Grounding the rotary-line-conductor 327 by pressing the button 41 once, produces an energizing of the rotary-line-relay 277 of the connector, which 40 latter, as is well known, causes the private-magnet 234 to attract its armature once, permitting the connector-side-switch to pass to second position. Then when the vertical-button 40 is pressed ten times the vertical-line-relay of the connector is again energized, and now, the side-switch being in 45 second position, the rotary-magnet 239 is operated ten times, rotating the wipers onto the tenth set of contacts of the second level 50 of the connector-banks. It is clear that in order for the subscriber at the sub-station #320 to call the sub-station #120 the connector must establish connection with a line that is in use and, therefore, with a line, the 55 connector-private-bank-contact of which, is normally protected by a guarding potential. It is with said contact that the private-wiper 203 of the connector is now in engagement. Therefore, when the subscriber 60 grounds the rotary-line-conductor 327 for the last time, by pressing the button 41, it would appear that the connector should be released, but this is not the case, because of a special provision. Attention has been 65 called to the fact that each time that the

rotary line is grounded at substation #320 the rotary-private-normal-relay 187 becomes energized. Furthermore, a guarding potential appears at the connector-private-banks over the private-normal 339 and normally 70 through the rotary-private-normal-relay-springs 193 and 192 from the ground terminal G⁴. Therefore, with such a construction it is evident that each time the rotary-private-normal-relay 187 becomes energized 75 the continuity of the circuit between the said ground terminal G⁴ and the private-normal-conductor 339 is interrupted at the rotary-private-normal-relay-springs 193 and 192, since said springs, while the said private-normal-relay is energized, are separated. The calling subscriber then upon pressing the rotary-button 41 for the last time not only causes the private-magnet 234 to attract its armature as before, but at the same 80 time removes the guarding potential from the private-bank-contact with which the private-wiper 203 is engaged, to prevent the connector from being released when the private-springs 245 and 246 are brought into 85 contact. When the rotary-button 41 is released and when the private-armature 235 returns to normal position the side-switch passes to third position with the wipers 255, 256, 257 and 258 in engagement with the contact-points 261, 264, 267 and 270. The engagement of the side-switch-wipers 257 and 258, respectively, with the contact-points 267 and 270 connects the extended subscriber's calling line-conductors 334 and 335 with 90 the normal-conductors 423 and 424 as usual; but since the said normal-conductors are connected, respectively, with the vertical and rotary line-conductors 321 and 327 of the calling line the calling subscriber is then in 95 position to signal back upon his own line, as will be described. The guarding potential, that is removed from the connector-private-banks when the rotary-private-normal relay is energized, is restored as soon as the connector-side-switch-wiper 256 finds the 100 grounded contact-point 264. It is evident 105 that after the connector has called back upon the calling line the private-normal 339 is grounded from both ends at ground-points 110 G⁴ and G⁶. When the side-switch-wiper 256 of the connector passes onto the contact-point 264 the pole-changing-relay 295 becomes energized through the sub-station 115 #320 and the rotary-private-normal-relay 187, connector-rotary-line-relay 277, and differential-relay-winding 291 in multiple. The 120 current passes from ground G⁶ through the side-switch-wiper 256, differential-relay-springs 299 and 300, pole-changing-relay 295, conductor 379, ringer-relay-springs 282 and 283, side-switch-wiper 258, contact-point 270, conductor 388, rotary-line-wiper 202, normal-conductor 424, then by one path 125 to the rotary-line-conductor 327, spring 43,

contact-point 44, conductor 380, sub-station relay-springs 23 and 22, conductor 381, springs 31 and 30, transmitter 8, primary winding 11 of the induction-coil 10, contact-point 17, spring 16, and springs 26 and 27, contact-point 45, spring 42, vertical-line-conductor 321, vertical-normal-conductor 423, line-wiper 201, conductor 402, contact-point 267, side-switch-wiper 257, ringer-relay-springs 286 and 285, conductor 422, retardation-coil 303 to the battery-lead 324 and through battery B to ground G. The other branch of the circuit reaches the non-grounded terminal of battery B by another path—that is, through the switch-shaft-springs 92 and 91, conductor 328, side-switch-wiper 169, contact-point 183, rotary-private-normal-relay 187, rotary-line-wiper 79, trunk-conductor 335, rotary-line-relay 277, winding 291 of the differential-relay 290, conductor 355, ringer-relay-springs 288 and 289, conductor 356, pole-changing-relay-springs 293 and 297, and through battery B to ground G. But as soon as the said pole-changing-relay becomes energized the spring 293 is separated from the spring 297 and closed in connection instead with the spring 296; therefore, this last multiple circuit is destroyed at once, leaving only the path through the sub-station #320. For this destroyed circuit is substituted another multiple circuit with the pole-changing-relay 295 as soon as the pole-changing-relay-springs 293 and 296 come into contact. This circuit starts at ground G* and extends through the contact-point 264, side-switch-wiper 256, conductors 363 and 412, pole-changing-relay-springs 296 and 293, conductor 356, ringer-relay-springs 289 and 288, winding 291 of the differential-relay 290, conductor 354, rotary-line-relay 277, rotary-trunk-conductor 335, rotary-line-wiper 79, rotary-private-normal-relay 187, contact-point 183, side-switch-wiper 169, conductor 328, switch-shaft-springs 91 and 92, and thence through the circuit that has been described through the transmitter 8 to the vertical-line-relay 271 and winding 292 of the differential-relay 290 through battery B to ground G. Thus the transmitter 8 at the sub-station #320 is provided with energizing current through a circuit which is, between the rotary-line-conductor 327 at the first-selector A and the connector ground terminal G*, a multiple circuit of two paths, one comprising the rotary-private-normal-relay 187, the rotary-line-relay 277, and the winding 291 of the differential-relay 290, and the other the pole-changing-relay 295. The first of these two circuits comprises the winding 291 of the differential-relay 290, as stated, but since the same circuit comprises the other differential-relay-winding 292 the magnetic effects are neutralized and the relay-armature 298 is not operated. The calling subscriber having connected the connector with his own line presses the signaling-button 15 and thereby grounds the vertical-line-conductor 321. Of course, when the spring 16 of the signaling device at the sub-station #320 leaves the contact-point 17, the energizing circuit through the transmitter 8 and through the pole-changing-relay 295, as well as through the rotary-line-relay 277 and the winding 291 of the differential-relay 290, is destroyed or opened for the time being. The vertical line being grounded when the push-button 15 forces the spring 16 onto the contact-point 18, the vertical-line-relay 271 is, therefore, again energized for well known reasons, and the connector-ringer-relay 280 is magnetized over circuits that have once been described. As soon as the ringer-relay-armature 281 is attracted, and when the ringer-relay-springs 283 and 286, respectively, engage the ringer-relay-springs 284 and 287, a ringing current from the generator J is then sent over the line-conductors 321 and 327 and through the sub-stations #220 and #120; but since the frequency of the said current is capable of making only the ringing apparatus at the sub-station #120 respond only the subscriber at that station, of course, will answer. The circuit traversed by the current extends as follows: from the brush 404 to the ringer-relay-springs 287 and 286, side-switch-wiper 257, contact-point 267, vertical-line-wiper 201, vertical-normal-conductor 423, vertical-line-conductor 321 through the sub-stations #120 and #220 to the rotary-line-conductor 327, rotary-normal-conductor 424, connector-rotary-line-wiper 202, contact-point 270, side-switch-wiper 258, ringer-relay-springs 283 and 284, brush 386 to the ringer-generator J.

It will be noticed that the separation of the differential-relay-springs 299 and 300 not only makes the release possible but also prevents the establishment of a circuit (when the pole-changing-relay-springs 293 and 297 reengage) through the pole-changing-relay 295, that would make a buzzer out of the latter. This circuit would extend from ground G* through the side-switch-wiper 256, differential-relay-springs 299 and 300, pole-changing-relay 295, ringer-relay-springs 282 and 283, side-switch-wiper 258, rotary-line-wiper 202, rotary-normal-conductor 424, rotary-line-conductor 327, switch-shaft-springs 92 and 91, conductor 328, side-switch-wiper 169, rotary-private-normal-relay 187, rotary-line-wiper 79, connector-rotary-line-relay 277, winding 291 of the differential-relay 290, conductor 355, ringer-springs 288 and 289, pole-changing-relay-springs 293 and 297 and through battery B to ground G. Obviously, as soon as the subscriber at the sub-station #320 restores his signaling-button 15, the normal

condition for providing the transmitter 8 with talking battery described before the subscriber pressed said signaling-button 15 is again restored. Then the pole-changing-relay 295 and the rotary-line-relay become reenergized, while the differential-relay and the ringing relay become deenergized. It will be borne in mind that while the differential-relay is deenergized the release-magnet 218 cannot be magnetized, even though the trunk-release-springs 275 and 276 be held in contact, because the energizing circuit through said magnet comprises, as already pointed out, the differential-relay-springs 301 and 302 which are normally held apart. When the subscriber at the substation #120 answers he removes his receiver 479 from the switch-hook 480 and thereby causes the springs 481 and 482 to close contact, as well as the springs 483, 484 and 485. Therefore, the transmitter 186 is bridged in series with the primary winding 11 of the induction-coil 10. Of course, it will be understood that the lockout relay of substation #120 energizes in the usual manner when the subscriber removes the receiver from the switch hook. This energizing circuit is already familiar. The said transmitters being bridged across the same line in series with their primary windings 487 and 11, respectively, as stated, and the receivers 479 and 2 being in series with the secondary windings 489 and 12 of the induction-coils 488 and 10, respectively, the subscribers will be able to communicate in a well-known manner. The first-selector A being connected through to the connector C and the latter having called back upon the calling line, then if the subscriber at the sub-station #220 removes his receiver his sub-station relay 464 will be energized and he will be prevented from using the line for the time being. This energizing circuit, as usual, is completed when the springs 465 and 466 come into contact at the same time that the springs 467 and 468 come into contact. The current passes from ground G through the springs 466 and 465, springs 468 and 467, conductor 470, substation relay 464, rotary-line-conductor 327, thence through a multiple circuit of two branches, one branch including the transmitter 8, and the other branch the transmitter 486, to the vertical-line-conductor 321, thence to the side-switch-wiper 168 and over a multiple circuit of two paths, the one path extending over the vertical-normal-conductor 423 to the vertical-line-wiper 201, side-switch-wiper 257, ringer-relay-springs 286 and 285, conductor 422, retardation-coil 303 to the battery-lead 324, and the other

circuit through the vertical-private-normal-relay 186, the vertical-line-relay 271 of the connector C, differential-relay-winding 292 to the battery-lead 324, thence through battery B to ground G. When the sub-station-relay 464 becomes energized the sub-station connection to ground is broken at the springs 490 and 491, as usual, thereby rendering the said sub-station non-interfering. The subscriber then puts his receiver to his ear and hears the two subscribers, the one at #320 and the other at #120, and understands, therefore, that the line is busy. He will restore his receiver and thereby release the sub-station relay in a well-known manner, and at a later time if he desires he can make the call. It will be understood, of course, that when the subscriber at substation #120 removes the receiver 479 from the switch-hook 480 an energizing circuit, similar to the circuit traced through the relay 464 of the substation #220, is closed through the substation relay. The said relay operates to break the ground connection between the substation calling device and the release springs, as explained. If the subscribers at substations #320 and #120 are through talking, then the calling subscriber may restore the switches by grounding the vertical and rotary line-conductors simultaneously when he hangs up his receiver. The grounding of the rotary-line-conductor 327 will short-circuit the pole-changing-relay 295 through ground, as well as the rotary-line-relay 277 and the winding 291 of the differential-relay 290, as already pointed out. This short-circuit or shunt will extend from ground at the calling substation to the rotary-line-conductor 327 and over a multiple circuit, to which reference has already been made, the one side of which includes the rotary-line-relay 277 and the winding 291 of the differential-relay 290, and the other side of which includes the pole-changing-relay 295, and thence through the side-switch-wiper 256 to the ground terminal G. The current through the winding 291 ceasing to flow, the differential-relay then becomes energized, and the pole-changing-relay becoming deenergized, the pole-changing-relay-springs 293 and 297 are then restored to normal position. As soon as the said spring 293 meets the spring 297 an energizing circuit through the rotary-line-relay 277 and the winding 291 of the differential-relay 290 is established, but in the opposite direction to the flow of current while the subscribers were talking; therefore, the differential-relay 290 already being magnetized is now more strongly magnetized than before, whereby the differential-relay-springs 301 and 302 are maintained together; and at the same time, since the rotary-line-relay 277 becomes energized also,

the trunk-release-springs 275 and 276 are so brought into contact that the connector-release-magnet 218 and first-selector back-release-relay 105 become energized in series. 5 This being the case, in a manner that is clear, and that has been dwelt upon, the connector and the first-selector become released because of the magnetizing and de-magnetizing of their release-magnets. The 10 release being accomplished, and the subscribers having restored their receivers, any other subscriber on the same line may now, if he desires, use the said line in a manner that is obvious.

15 Although the foregoing novel features and combinations can, of course, be employed for any suitable or desired purpose, it is nevertheless true that practically all of the described changes and matters of improvement have been made primarily for the purpose of adapting the features of my said prior application to common battery work. For example, the sub-station relay 19 (see Fig. 1) is in this case not only provided with the ground circuit controlling springs 20 and 21, but is also given two other springs 22 and 23 for controlling the normal energizing circuit of the transmitter 20. Again, the switch-hook cam-arm 6 controls the ground-springs 35 and 34, substantially as in said prior application; but in this case the cam-arm 5 not only controls the ringing circuit through the spring 24, and incidentally the continuity of the circuit between the rotary and vertical sides of the line (by the springs 26 and 27), but also controls the two springs 28 and 29 instead of the three springs of said prior application. These springs 28 and 29, and the 25 springs 32 and 33, controlled by the cam-arm 7, combine to determine the energizing circuit through the sub-station relay 19 when the switch-hook is raised to a given point. Furthermore, when the switch-hook 30 is down the said energizing circuit is then open at the said springs 28 and 29; and when the hook is up this circuit is open at the springs 32 and 33; but only at some intermediate point is the energizing circuit closed 35 for the coil 19. Also, in my present invention, it will be seen that both cam-arms 7 and 5 exert a controlling influence over said energizing circuit; for with the arrangement shown, the cam-arm 7 is made to control two springs in addition, namely the springs 30 and 31. When the switch-hook is down the transmitter circuit is then open at the springs 30 and 31 as well as at the springs 26 and 27. Obviously, this construction is 40 desirable in order that the relay 19 may not vibrate or chatter when the springs 32, 33, and 28, 29 are closed while the line is out of use, and, therefore, while the rotary-line-conductor 327 is open at the first-selector-switch-shaft-springs 91 and 92. Evidently,

and preferably, the circuit which might energize the relay 19 and cause it to objectionably vibrate or chatter must contain some switch-point under the control of the said relay itself. Looking at the drawings, it 45 will be seen that such is the case, inasmuch as the contact-points 22 and 23 are in this circuit which would extend from ground (G) through the springs 32 and 33 and the springs 28 and 29, through the coil of the 50 relay 19, relay-springs 23 and 22, transmitter 8 (should the springs 30 and 31 at this time be closed), vertical-line-conductor 321, and thence to the non-grounded terminal of the battery B.

55 With the foregoing arrangement, it is evident that the transmitter 8 when in use, and while relay 19 is not energized, receives energizing current from the rotary-line-conductor 327, spring 43, contact-point 44, conductor 380, sub-station relay-spring 23, spring 22, springs 31 and 30, substantially as previously described; but when the relay 19 is energized, and since the springs 22 and 23 are then separated, the current at such 60 time passes from the rotary-line-conductor 327 through the spring 23, coil 19, springs 29 and 28, springs 32, 31 and 30 to the transmitter 8, and through the vertical-line-conductor 321 to the battery B, as previously 65 described. It will also be observed that while the relay 19 is not energized, and while the switch-hook 3 is up at sub-station #320, for example, the said relay 19 is short-circuited or shunted. The thus 70 shunted circuit begins, of course, with the sub-station relay-spring 23 and extends through the said relay 19, springs 29, 28, springs 32, 31, conductor 381, and thence through the spring 22 and back to the spring 75 23. With the arrangement shown and described, the subscribers on a party-line are given a plurality of non-interfering telephone sub-station equipments, the microphone transmitters of these sub-stations all 80 being connected in multiple and receiving current from the common battery or centralized source of electrical current supply. In addition, the said microphone transmitters are connected in series with the ringing 85 buttons, and these serially connected ringing-keys and microphone transmitters are combined with the features for making the different party-line stations non-interfering in character, as previously described. It 90 will also be seen that the arrangement involves a subscriber's sub-station relay controlling the ground-circuit and the transmitter normal circuit. Consequently, the transmitter is in the same circuit with a sub-station relay that controls the ground and transmitter normal circuit; and it will also be seen that the sub-station relay is energizable through the transmitter of any sub-station on the line; and as a further consid- 95

eration, it will be seen that the arrangement involves a sub-station relay controlled by the switch-hook thereof and shunted or paralleled by a condenser.

5 The first-selector, which may be of the general type set forth in Patent No. 815,321 granted on the 13th day of March, 1906, to Keith, Erickson and Erickson, has two private-normal-relays 186 and 187 that are es-
10 sential only when one subscriber calls back on his own line, after the flow of talking current pulls up the rotary-private-normal-relay and opens up the ground to the private-normal; and the vertical-private-nor-
15 mal-relay which is energized at the same time restores the ground connection thus destroyed or opened up, in order that no other subscriber may then come in on the calling line. Again, with the construction
20 and circuit arrangement described, the system involves a sub-station relay which is energized in multiple or parallel with the connector-pole-changing-relay and which supplies the transmitter with current. It will
25 also be observed that the sub-station relay, as, for example, the sub-station relay 464, has seven energizing circuits, all as previously described. Referring to Fig. 1, it
30 will be seen that one of said circuits is tem-
porarily established when the subscriber at sub-station #220 removes his receiver after another subscriber on the same line has removed his, and before the first-selector is operated. Another of these circuits is tem-
35 porarily established under the same conditions after the first-selector-switch-shaft has been raised and before it has been rotated, and, therefore, while the side-switch is in first position. Still another of these
40 circuits is closed temporarily while the first-selector-side-switch is in second position; and the fourth of said circuits occurs while the first-selector-side-switch is in third position and before a called subscriber on an-
45 other line has answered. The fifth circuit occurs after the called subscriber has an-
50 swered. A sixth circuit is then formed when the connector calls back upon the calling line, and before the called subscriber has answered; and the seventh occurs after the called subscriber has answered on the same line. In the last case, it will be seen the sub-station relay 464 is energized over a circuit comprising the transmitters 8 and 486 of the calling and called subscribers in multiple.

In the connector, which may be of the general type set forth in Patent No. 815,176 granted on the 13th day of March, 1906,
60 to Keith, Erickson and Erickson, it will be seen that the two additional differential-relay-springs 299 and 300 are provided not only to accomplish the release of the switches, as previously described, but also for the purpose of preventing the pole-

changing-relay 295 from becoming objectionably vibratory under certain conditions. As previously explained, a peculiar energizing circuit is established through the pole-changing-relay 295 when the connector calls back 70 upon the calling line.

It will be readily understood that the various instruments, coils, devices, etc. can be constructed and adjusted to suit the requirements of different cases and with a view to 75 accomplishing the results and operations set forth and described.

In order that any calling subscriber may selectively ring or signal any particular subscriber on a party-line, differently tuned or otherwise selectively adjusted bells can be employed at the sub-stations on the party-lines of the system, and the exchange can be equipped with different classes of connectors, each class having allotted to it a 85 ringing generator of a certain frequency. This, however, is all fully described in my prior application No. 270,591 filed by me in the United States Patent Office on July 20, 1905, for improvement in party-line tele- 90 phone systems, of which this present application is an improvement and need not be further described.

It will be observed that the relay at sub-station #230 is receiving current through 95 its allotted transmitter, and that this flow of current may be sufficient to keep the relay energized. As a matter of precaution, however, and with a view to making the lock-out relays more certain in action, it is desirable 100 to provide each one with a locking spring for engaging and holding the armature in its attracted position, as illustrated at sub-station #230. Furthermore, and as previously made to appear, there are times when 105 the relays are without an energizing circuit, either temporary or permanent—after the relay has been temporarily energized to prevent the subscriber from using the line—and at such time the locking spring for the 110 relay-armature is necessary in order to prevent the cessation of current through the relay from deenergizing it, and from thereby perhaps causing an undesirable interference with the desires of the subscriber or 115 subscribers already in possession of the line.

It should also be taken into account that the current, for example, which is flowing through the relay 427 is also flowing through several other relays and coils in the line-circuit at the exchange, and that for this reason such flow of current might not be strong enough to operatively energize the said relay.

With the arrangement shown, the cen- 125 tralized source of switching and talking current B may be of about 50 volts, and the resistance of the different coils and relays may be as follows: The sub-station-relay 2500 ohms; the connector-line-relays 125

ohms each; the windings of the differential-relay 250 ohms each; the pole-changing-relay and the retardation-coil 375 ohms each; all release-magnets, vertical-magnets 5 and rotary-magnets 60 ohms each; the private-magnets 350 ohms each; the first-selector-bridge-cut-off-relays about 2000 ohms each; the connector-ringer-relay 500 ohms; the first-selector-private-normal-relays 125 10 ohms each; and the selector's back-release-relay 1/2 ohm. Obviously, however, and as previously stated, the strength of the current and the different resistances can be adjusted to suit the requirements of different 15 cases, as will be readily understood by those skilled in the art.

What I claim as my invention is:—

1. A telephone system comprising a subscriber's line, a plurality of sub-stations on 20 said line, means at each sub-station for transmitting the electrical impulses necessary for calling any other subscriber on the same line, or in the same system, trunk-selecting and line-connecting machinery at 25 the central station controlled by the said subscribers through the medium of said impulse-transmitting means, a centralized source of electrical current supply for furnishing current to the said line for switching 30 and signaling and talking purposes, and relay means located at each of said sub-stations, together with additional means for operating with said relay means and whereby one subscriber cannot interfere with the 35 other in the use of said line.

2. An automatic common-battery non-interfering party-line telephone system comprising a line, a plurality of subscribers' stations on said line, subscriber-controlled 40 means for establishing connection between any two of said sub-stations, a centralized source of switching and talking current, and subscriber-controlled automatic means for preventing one subscriber from interfering 45 with the other in the use of said line.

3. A telephone system comprising a subscriber's line, a plurality of sub-stations on said line, subscriber-controlled automatic switching means for establishing connection 50 between any two of said sub-stations, or between any one of said sub-stations and any other sub-station in the system, a centralized source of talking and switching current, and relays located at said sub-stations, together 55 with suitable circuits and subscriber-operated devices whereby said relays are operative to prevent any subscriber on the said line from using the latter when the same is already in use between other subscribers.

4. In a telephone system, the combination of a party-line, a plurality of sub-stations on said line, subscriber-controlled automatic switching means for establishing connection 65 between any two of said sub-stations, or be-

tween one of said sub-stations and any other sub-station of the system, microphone transmitters at the said sub-stations, a centralized source of switching current adapted also for supplying talking current to said transmitters, and automatic electro-magnetic means operated by current from said source of supply and adapted to prevent any subscriber on the said line from making use thereof when the same is already in service 70 between other subscribers.

5. An automatic telephone system comprising a subscriber's microphone transmitter, a centralized source of talking current, a line-circuit including said transmitter and source of current in series, a subscriber's relay controlling the line-circuit extending through said transmitter, and subscriber-controlled automatic switching means for establishing connection with the sub-station of 80 any called subscriber.

6. In a telephone system, the combination of a subscriber's line, a plurality of sub-stations thereon, a connector provided with a differential-relay, a centralized source of 90 current for supplying current through the coils of said relay to the said line for talking purposes, a local release-circuit controlled by said differential-relay, subscribers' transmitters located at said sub-stations and receiving talking current from said source of current supply, subscriber-operated means at each sub-station for controlling the operations of said connector, and automatic means located at the said sub-stations and adapted to prevent seizure of the line by any subscriber thereon when the same is already 95 in service between other subscribers.

7. An automatic telephone system comprising a line-circuit, a microphone transmitter in said circuit, a ringing key in said circuit, a relay associated with and controlling the flow of current through said transmitter and ringing key, a centralized source of switching and talking current, and subscriber-controlled automatic switching means for establishing connection with the sub-station 100 of any called subscriber.

8. An automatic telephone system comprising a ground-circuit, a microphone 115 transmitter at the sub-station, a normal line circuit for said transmitter, a relay located at the sub-station and controlling both of said circuits, a centralized source of switching and talking current, and subscriber-controlled automatic switching means for establishing connection with the sub-station of 120 any called subscriber.

9. A telephone system comprising a sub-station having a receiver switch-hook, the 125 receiver being temporarily removed from said hook, a microphone transmitter, a line-circuit, a centralized source of switching and talking current temporarily connected in a closed line-circuit in series with said 130

- transmitter, a sub-station relay provided with circuit-controlling contacts, the coil of said relay being temporarily connected in series with said transmitter, and subscriber-controlled automatic means for establishing connection with the sub-station of any called subscriber, together with subscriber-controlled automatic means for producing an audible call-signal at the sub-station of any called subscriber.
10. An automatic telephone system comprising a subscriber's sub-station relay, ground and metallic circuits controlled by said relay, a subscriber's sub-station microphone transmitter, a centralized source of switching and talking current, and an energizing circuit for said relay including said transmitter.
11. A telephone system comprising a subscriber's sub-station relay provided with an armature, a switch-hook provided with means for controlling said armature, a condenser connected in parallel with the coil of said relay, subscriber-controlled switching machinery at the exchange or central station, adapted for use by calling subscribers in automatically establishing connection with the lines of the called subscribers, and line circuits for controlling said switching machinery, said line circuits controlled by said relay, substantially as and for the purpose set forth.
12. An automatic telephone system comprising a shaft, a pair of shaft line-wipers, a side-switch having a pair of line-wipers, a pair of private-normal-relays having coils connecting the shaft wipers with the side-switch-wipers, said coils thereby constituting part of the main line-circuit, and a private-normal provided with normally-open and normally-closed switch-points connected in parallel and controlled by said private-normal-relays.
13. An automatic telephone system comprising a subscriber's sub-station relay, a connector-pole-changing-relay, a centralized source of talking and switching current, means to be switched from one pole of the battery to the other by said pole-changing-relay, a subscriber's sub-station transmitter, and a circuit by which the sub-station relay is energized in multiple or parallel with the connector-pole-changing-relay, and whereby the current is supplied to the transmitter through the said relay.
14. A subscriber's sub-station relay, a sub-station transmitter, a plurality of energizing circuits for said relay, each circuit including said transmitter, subscriber-controlled switching machinery at the exchange or central station, adapted for use by calling subscribers in automatically establishing connection with the lines of the called subscribers, and line circuits for controlling said switching machinery, said line circuits controlled by said relay, substantially as and for the purpose set forth.
15. An automatic telephone system comprising a subscriber's sub-station relay, a line-circuit, a centralized source of switching and talking current, a plurality of subscribers' microphone transmitters connected with the said line-circuit, and an energizing circuit for said relay including said transmitters in multiple.
16. In a telephone system, the combination of subscriber-controlled automatic switching means for establishing connection with the sub-station of any called subscriber, a line-circuit, a centralized source of switching and talking current, a couple of microphone transmitters temporarily connected in parallel in said circuit, a third transmitter temporarily connected in parallel with the other transmitters, and a subscriber's sub-station relay allotted to the said third transmitter and having its coil temporarily connected in series therewith.
17. An automatic telephone system comprising a connector having a differential-relay provided with a pair of normally-open switch-springs, a release-circuit controlled by said switch-springs, a pair of normally-closed switch-springs, a pole-changing-relay, a circuit for said pole-changing-relay controlled by said normally-closed switch-springs, a centralized source of operating and talking current, means including a circuit for controlling said connector, means controlled by said pole-changing-relay for switching said circuit from one pole of said source of current to the other.
18. A telephone system comprising a party-line, a plurality of sub-stations on said line, a normally hung up receiver at each sub-station, a relay at each sub-station, subscriber-controlled automatic means for establishing connection with the sub-station of any called subscriber, circuits controlled by said relays, and means whereby the taking down of any receiver will energize the relay of the same sub-station if any other receiver on the same line is down.
19. A telephone system comprising a party-line, a plurality of sub-stations on said line, a normally hung up receiver at each sub-station, a relay at each sub-station, a ground connection located at each sub-station and controlled by the relay thereof, and means whereby the taking down of any receiver will energize its allotted relay if the receiver is already down at some other sub-station on the same line.
20. A telephone system comprising a party-line, a plurality of sub-stations thereon, subscriber-controlled automatic means for establishing connection with the sub-station of any called subscriber, a lock-out relay at each sub-station, a normally hung

- up receiver at each sub-station, circuits provided with switch contacts actuated by said relays, a plurality of energizing circuits for each relay, and means cooperating with said 5 relays to give any subscriber on the line exclusive possession thereof for switching purposes as soon as he takes down his receiver, the different energizing circuits of each relay extending through the different sub- 10 stations.
21. A telephone system comprising a party-line, a plurality of sub-stations on said line, a relay at each sub-station, circuits provided with switch contacts actuated 15 by said relays, normally hung up receivers at each of said sub-stations, and means whereby any one of said relays is energizable by the taking down of its allotted receiver as soon as any other receiver is down 20 at some other sub-station on the same line.
22. A telephone system comprising a party-line, a plurality of sub-stations on said line, subscriber-controlled automatic means for establishing connection with the 25 sub-station of any called subscriber, a lock-out relay at each sub-station, and a plurality of energizing circuits for each relay, each of said energizing circuits including the two sides of the said line in parallel.
23. A telephone system comprising a party-line, a plurality of sub-stations thereon, subscriber-controlled automatic switching means for establishing connection with the sub-station of any called subscriber, a 35 centralized source of switching and talking current, a lock-out relay at each sub-station, and an energizing circuit for each relay, each of said energizing circuits including the two sides of the said line in parallel.
24. A telephone system comprising a party-line, a plurality of sub-stations on said line, subscriber-controlled automatic means for establishing connection with the sub-station of any called subscriber, a relay 45 at each sub-station, a ground connection located at each sub-station and controlled by the relay thereof, and a plurality of energizing circuits for each relay, one or more of said energizing circuits including the 50 two sides of the line in parallel.
25. A telephone system comprising a party-line, a plurality of sub-stations on said line, subscriber-controlled automatic switching means for establishing connection 55 with the sub-station of any called subscriber, a relay at each sub-station, a ground connection located at each sub-station and controlled by the relay thereof, and a plurality of energizing circuits for each relay, one or 60 more of said energizing circuits including the two sides of the line in parallel, together with a centralized source of switching and talking current.
26. A telephone system comprising a calling subscriber's line, a connector provided 65
- with a pole-changing-relay, a battery, an operating circuit to be switched by said pole-changing-relay from one pole of said battery to the other, calling and called subscribers' stations connected together by the 70 said calling line, and an energizing circuit for said relay including both sides of the said line.
27. A telephone system comprising a calling subscriber's line, a connector provided 75 with a pole-changing-relay, a battery, an operating circuit to be switched by said relay from one pole of said battery to the other, and an energizing circuit for said relay including both sides of the said calling 80 line.
28. A telephone system comprising a party-line, a plurality of sub-stations thereon, lock-out means at each sub-station, and a plurality of talking circuits for each sub- 85 station, one talking circuit being closed when the subscriber is in possession of the line for switching purposes, the other talking circuit being closed when the subscriber is locked out by reason of the line being in the possession 90 of some other subscriber.
29. A telephone system comprising a party-line, a plurality of sub-stations thereon, lock-out means at each sub-station, a plurality of talking circuits for each sub-station, subscriber-controlled automatic switching 95 means for establishing connection with any called subscriber, and a centralized source of switching and talking current, one talking circuit being closed when the subscriber is in possession of the line for switching purposes, the other talking circuit being closed when the subscriber is locked out by reason of the line being in the possession 100 of some other subscriber.
30. A telephone system comprising a party-line, a plurality of sub-stations thereon, subscriber-controlled automatic means for establishing connection with the sub-station of any called subscriber, a relay at 110 each sub-station, a transmitter at each sub-station, and a plurality of energizing circuits for each relay, the energizing circuits of any relay each including the transmitter of a different sub-station. 115
31. A telephone system comprising a party-line, a plurality of sub-stations thereon, subscriber-controlled automatic switching means for establishing connection with the sub-station of any called subscriber, a relay at each sub-station, a transmitter at each sub-station, and a plurality of energizing circuits for each relay, the energizing circuits of any relay including the transmitter of a different sub-station, together with a centralized source of switching and talking current. 120
32. A telephone system comprising a party-line, a plurality of sub-stations thereon, a lock-out relay at each sub-station, a 130

- hook-switch at each sub-station, and an energizing circuit for each relay, each energizing circuit being provided with two switch-points controlled by the hook-switch of the 5 same sub-station, together with subscriber-controlled automatic switching means for establishing connection with the sub-station of any called subscriber, and a centralized source of switching and talking current.
- 10 33. A telephone system comprising a party-line, a plurality of sub-stations thereon, a lock-out relay at each sub-station, a hook-switch at each sub-station, and an energizing circuit for each relay, each energizing circuit being provided with two normally-open switch-points controlled by the hook-switch of the same sub-station, together with subscriber-controlled automatic switching means for establishing connection 15 with the sub-station of any called subscriber, and a centralized source of switching and talking current.
34. A telephone system comprising a party-line, a plurality of sub-stations thereon, subscriber-controlled automatic switching means for establishing connection with the sub-station of any called subscriber, a transmitter at each sub-station, a hook-switch at each sub-station, a receiver normally resting upon each hook-switch, a centralized source of switching and talking current, and a circuit for each transmitter, together with sub-station lock-out relays provided with energizing circuits controlled by 25 themselves and by the hook-switches, each transmitter-circuit having two normally-open switch-points controlled by the hook-switch of the same sub-station.
35. A telephone system comprising a party-line, a plurality of sub-stations thereon, subscriber-controlled automatic switching means for establishing connections with the sub-station of any called subscriber, a transmitter at each sub-station, a hook-switch at each sub-station, a receiver normally resting upon each hook-switch, a centralized source of switching and talking current, and a circuit for each transmitter, each transmitter-circuit having two normally-open switch-points controlled by the hook-switch of the same sub-station, the said subscriber-controlled means comprising a connector provided with a differential-relay, a switch releasing circuit controlled by said differential-relay, and a pole-changing-relay adapted when energized to switch the source of current in series between the windings of said differential-relay.
36. A telephone system comprising a party-line, a plurality of sub-stations thereon, subscriber-controlled automatic switching means for establishing connection with the sub-station of any called subscriber, a transmitter at each sub-station, a hook-switch at each sub-station, a receiver normally resting upon each hook-switch, a centralized source of switching and talking current, and a circuit for each transmitter, each transmitter-circuit having two normally-open switch-points controlled by the hook-switch of the same sub-station, the said subscriber-controlled means comprising a connector provided with a differential-relay, a switch releasing circuit controlled by said differential-relay, and a pole-changing-relay adapted when energized to switch the source of current in series between the windings of said differential-relay.
37. A telephone system comprising a party-line, a plurality of sub-stations thereon, subscriber-controlled automatic switching means for establishing connections with the sub-station of any called subscriber, a switch-hook at each sub-station, a lock-out relay at each sub-station, and connections for short-circuiting or shunting each relay as soon as its allotted switch-hook is raised, together with a centralized source of switching and talking current.
38. A telephone system comprising a subscriber's station, subscriber-controlled automatic switching means for establishing connection with the sub-station of any called subscriber, a sub-station relay, a subscriber's switch-hook, a centralized source of switching and talking current, and means whereby the said relay is short-circuited or shunted when the switch-hook is permitted to rise.
39. A telephone system comprising a subscriber's line, a plurality of sub-stations on said line, subscriber-controlled automatic switching means for establishing connection between any two of said sub-stations, or between any one of said sub-stations and any other sub-station in the system, a centralized source of talking and switching current, and relays located at said sub-stations, together with suitable circuits and subscriber-operated devices whereby said relays are operative to prevent any subscriber on the said line from using the latter when the same is already in use between other subscribers, the said subscriber-controlled means comprising a connector provided with a differential-relay, a switch releasing circuit controlled by said differential-relay, and a pole-changing relay adapted when energized to switch the source of current in series between the windings of said differential-relay.
40. In a telephone system, the combination of a party-line, a plurality of sub-stations on said line, subscriber-controlled automatic switching means for establishing connection between any two of said sub-stations, or between one of said sub-stations and any other

- sub-station of the system, microphone transmitters at the said sub-stations, a centralized source of switching current adapted also for supplying talking current to said transmitters, and automatic electro-magnetic means operated by current from said source of supply and adapted to prevent any subscriber on the said line from making use thereof when the same is already in service 5 between other subscribers, the said subscriber-controlled means comprising a connector provided with a differential-relay, a switch releasing circuit controlled by said differential-relay, and a pole-changing-relay 10 adapted when energized to switch the source of current in series between the windings of said differential-relay.
41. An automatic telephone system comprising a subscriber's microphone transmitter, a centralized source of talking current, a line-circuit including said transmitter and source of current in series, a subscriber's relay controlling the line-circuit extending through said transmitter, and subscriber-controlled automatic switching means for 15 establishing connection with the sub-station of any called subscriber, the said subscriber-controlled means comprising a connector provided with a differential-relay, a switch releasing circuit controlled by said differential-relay, and a pole-changing-relay adapted when energized to switch the source of current in series between the windings of said differential-relay.
42. An automatic telephone system comprising a line-circuit, a microphone transmitter in said circuit, a ringing key in said circuit, a relay associated with and controlling the flow of current through said 20 transmitter and ringing key, a centralized source of switching and talking current, and subscriber-controlled automatic switching means for establishing connection with the sub-station of any called subscriber, the said subscriber-controlled means comprising a connector provided with a differential-relay, a switch releasing circuit controlled by said differential-relay, and a pole-changing-relay adapted when energized to switch the source of current in series between the windings of said differential-relay.
43. An automatic telephone system comprising a ground-circuit, a sub-station, a microphone transmitter at the sub-station, a normal line circuit for said transmitter, a relay located at the sub-station and controlling both of said circuits, a centralized source of switching and talking current, and subscriber-controlled automatic switching 25 means for establishing connection with the sub-station of any called subscriber, the said subscriber-controlled means comprising a connector provided with a differential-relay, a switch releasing circuit controlled by said 30 differential-relay, and a pole-changing-relay adapted when energized to switch the source of current in series between the windings of said differential-relay.
44. In a telephone system, the combination of subscriber-controlled automatic switching means for establishing connection with the sub-station of any called subscriber, a line-circuit, a centralized source of switching and talking current, a couple of microphone transmitters temporarily connected in parallel in said circuit, a third transmitter temporarily connected in parallel with the other transmitters, and a subscriber's sub-station relay allotted to the said third transmitter and having its coil 35 temporarily connected in series therewith, the said subscriber-controlled means comprising a connector provided with a differential-relay, a switch releasing circuit controlled by said differential-relay, and a pole-changing relay adapted when energizing to switch the source of current in series between the windings of said differential-relay.
45. A telephone system comprising a party-line, a plurality of sub-stations thereon, subscriber-controlled automatic switching means for establishing connection with the sub-station of any called subscriber, a centralized source of switching and talking current, a lock-out relay at each sub-station, and an energizing circuit for each relay, each of said energizing circuits including the two sides of the said line in parallel, the said subscriber-controlled means comprising 40 a connector provided with a differential-relay, a switch releasing circuit controlled by said differential-relay, and a pole-changing-relay adapted when energized to switch the source of current in series between the windings of said differential-relay.
46. A telephone system comprising a party-line, a plurality of sub-stations on said line, subscriber-controlled automatic switching means for establishing connection with the sub-station of any called subscriber, a relay at each sub-station, a ground connection located at each sub-station and controlled by the relay thereof, and a plurality of energizing circuits for each relay, 45 including the two sides of the line in parallel, together with a centralized source of switching and talking current, the said subscriber-controlled means comprising a connector provided with a differential-relay, a switch 50 releasing circuit controlled by said differential-relay, and a pole-changing-relay adapted when energized to switch the source of current in series between the windings of said differential-relay.
47. A telephone system comprising a party-line, a plurality of sub-stations there-

- on, lock-out means at each sub-station, a plurality of talking circuits for each sub-station, subscriber-controlled automatic switching means for establishing connection 5 with any called subscriber, and a centralized source of switching and talking current, one talking circuit being closed when the subscriber is in possession of the line for switching purposes, the other talking circuit being closed when the subscriber is locked out by reason of the line being in the possession of some other subscriber, the said subscriber-controlled means comprising a connector provided with a differential-relay, a switch releasing circuit controlled by said differential-relay, and a pole-changing-relay adapted when energized to switch the source of current in series between the windings of said differential-relay.
- 20 48. A telephone system comprising a party-line, a plurality of sub-stations thereon, subscriber-controlled automatic switching means for establishing connections with the sub-station of any called subscriber, a relay at each sub-station, a transmitter at each sub-station and a plurality of energizing circuits for each relay, the energizing circuits of any relay each including the transmitter of a different sub-station, together with a centralized source of switching and talking current, the said subscriber-controlled means comprising a connector provided with a differential-relay, a switch releasing circuit controlled by said differential-relay, and a pole-changing-relay adapted when energized to switch the source of current in series between the windings of said differential-relay.
49. A telephone system comprising a party-line, a plurality of sub-stations thereon, a lock-out relay at each sub-station, a hook-switch at each sub-station, and an energizing circuit for each relay, each energizing circuit being provided with two switch-points controlled by the hook-switch of the same sub-station, together with subscriber-controlled automatic switching means for establishing connection with the sub-station of any called subscriber, and a centralized source of switching and talking current, the said subscriber-controlled means comprising a connector provided with a differential-relay, a switch releasing circuit controlled by said differential-relay, and a pole-changing-relay adapted when energized to switch the source of current in series between the windings of said differential-relay.
50. A telephone system comprising a calling subscriber's line, a connector temporarily set on said line to give connection with another sub-station on the same line, and a centralized source of switching and talking current, said connector having a pair of voice-current-conductors normally both connected in parallel with the same pole of the said source of current, a pole-changing-relay temporarily energized to switch the source of current in series between the said voice-current-conductors, and an energizing circuit for said relay including the sub-station of the calling subscriber.
51. A telephone exchange system comprising a party-line, a plurality of sub-station common battery transmitters bridged across the said line, each bridge being normally open, automatic switching means for establishing trunk connection with the said line, subscriber-controlled means for producing an audible call-signal at any called sub-station on the said line, a common battery or centralized source of switching and talking current, means for releasing the calling connection, and means for preventing a release of the calling connection by another subscriber on the same line. 85
52. A telephone exchange system comprising a group of party-lines, a plurality of sub-station common battery transmitters connected with each of said lines, the circuit of each transmitter being normally open, 90 automatic switching means for establishing trunk connection with one of said lines and thereby to the sub-station of any transmitter on said line, or with the line of any other sub-station in the same group, a common 95 battery or centralized source of switching and talking current means for releasing the calling connection, and means for preventing a release of the calling connection by another subscriber on the same line. 100
53. In a telephone system, a party line, a common battery for talking purposes, automatic means by which a calling subscriber establishes communication with the called subscriber, and automatic means for preventing the subscribers on the said line interfering with an established connection. 105
54. In a telephone system, a party line, a common battery for talking purposes, automatic means for trunking between subscribers, and automatic means for preventing the subscribers on said line interfering with an established connection. 110
55. In a telephone system, a party line, a common battery for talking purposes, automatic means by which a calling subscriber establishes communication with the called subscriber, and automatic means for preventing the subscribers on the said line interfering with an established connection, 115 both of said means operated by current from said battery.
56. In a telephone system, a party line, a common battery for talking purposes, automatic means for trunking between subscribers, and automatic means for preventing the subscribers on said line interfering with an established connection, both of said means operated by current from said battery. 120
- 130

57. In a telephone system, a party line, a common battery for talking purposes, automatic means for trunking between subscribers, and automatic means including relays at the different substations for preventing the subscribers on said line interfering with an established connection.
58. A telephone system comprising a line, a group of substations for said line, a common battery for talking purposes, automatic means for extending connection from said line, and automatic means for locking out all other substations of the group when one substation thereof is using said line, so as to prevent interference with an established connection.
59. A telephone system comprising a line, a group of substations to which said line is common, automatic means for trunking said line into connection with a second line, a common battery for talking purposes, and automatic means for locking out all other substations in the group when one substation thereof is using the line, so as to prevent interference with an established connection.
60. In a telephone system, a party line, a common battery for talking purposes, automatic means for trunking between subscribers, and automatic means including relays at the different substations for preventing the subscribers on said line interfering with an established connection, both of said automatic means operated by current from said battery or common source of talking current.
61. A telephone system comprising a line, a group of substations for said line, a common battery for talking purposes, automatic means for extending connection from said line, and automatic means for locking out all other substations of the group when one substation thereof is using the said line, so as to prevent interference with an established connection, both of said automatic means operated by current from said battery or common source of talking current.
62. A telephone system comprising a line, a group of substations to which said line is common, automatic means for trunking said line into connection with a second line, a common battery for talking purposes, and automatic means for locking out all other substations in the group when one substation thereof is using the line, so as to prevent interference with an established connection, both of said automatic means operated by current from said battery or common source of talking current.
63. In a telephone system, the combination of lines, automatic trunking machinery, a common battery for talking purposes, and for operating said machinery, automatic means for preventing interference between subscribers on the same line in the use of said trunking machinery, and means by which the subscribers control the flow of current in the lines for both operating and talking purposes.
64. In a telephone system, automatic trunking means, a series of relays for preventing the subscribers on a party line interfering with an established connection, circuits directly controlled by said relays, and a common battery for talking purposes, and for operating the automatic trunking means.
65. A telephone system comprising a subscriber's line, a plurality of substations on said line, means at each substation for transmitting the electrical impulses necessary for calling any other subscriber on the same line, or in the same system, trunk-selecting and line-connecting machinery at the central station controlled by the said subscribers through the medium of said impulse-transmitting means, including means having vertical motion to select groups and rotary motion to connect with a line in the selected group, a centralized source of electrical current-supply for furnishing current to the said line for switching and signaling and talking purposes, relay means located at each of said substations, and additional means co-operating with said relay means for preventing interference by one subscriber with the other in the operative use of said line.
66. An automatic common battery non-interfering party-line telephone system comprising a line, a plurality of subscribers' stations on said line, subscriber-controlled means for establishing connection between any two of said substations, including means having vertical motion to select groups and rotary motion to connect with a line in the selected group, a centralized source of switching and talking current, and subscriber-controlled automatic means for preventing one subscriber from interfering with the connection established by another on said line.
67. A telephone system comprising a subscriber's line, a plurality of substations on said line, subscriber-controlled automatic switching means for establishing connection between any two of said substations, or between any one of said substations and any other substation in the system, including means having vertical motion to select groups and rotary motion to connect with a line in the selected group, a centralized source of talking and switching current, relays located at said substations, and suitable circuits and subscriber-operated devices whereby said relays are operative to prevent any subscriber on the said line from making a call from the latter when the same is already in use between other subscribers or to release a connection.
68. In a telephone system, the combination

of a party-line, a plurality of substations on said line, subscriber-controlled automatic switching means for establishing connection between any two of said substations, or between one of said substations and any other substation of the system, including means having vertical motion to select groups and rotary motion to connect with a line in the selected group, microphone transmitters at the said substations, a centralized source of switching current adapted also for supplying talking current to said transmitters, and automatic electromagnetic means operated by current from said source of supply and adapted to prevent any subscriber on the said line from making use thereof to make a call when the same is already in service between other subscribers.

69. An automatic telephone system comprising a subscriber's microphone transmitter, a centralized source of talking current, a line circuit including said transmitter and source of current in series, a subscriber's relay controlling the line circuit extending through said transmitter, and subscriber-controlled automatic switching means for establishing connection with the substation of any called subscriber, including means having vertical motion to select groups and rotary motion to connect with a line in the selected group.

70. An automatic telephone system comprising a line circuit, a microphone transmitter in said circuit, a ringing key in said circuit, a relay associated with and controlling the flow of current through said transmitter and ringing key, a centralized source of switching and talking current, and subscriber-controlled automatic switching means for establishing connection with the substation of any called subscriber, including means having vertical motion to select groups and rotary motion to connect with a line in the selected group.

71. An automatic telephone system comprising a ground circuit, a substation having a relay controlling said ground circuit, a microphone transmitter at the substation, a normal line circuit for said transmitter, a relay located at the substation and controlling both of said circuits, a centralized source of switching and talking current, and subscriber-controlled automatic switching means for establishing connection with the substation of any called subscriber, including means having vertical motion to select groups and rotary motion to connect with a line in the selected group.

72. A telephone system comprising a substation having a receiver switch-hook, the receiver being temporarily removed from said hook, a microphone transmitter, a line circuit, a centralized source of switching and talking current temporarily connected in a

closed line circuit in series with said transmitter, a substation relay provided with circuit-controlling contacts, the coil of said relay being temporarily connected in series without said transmitter, subscriber-controlled automatic means for establishing connection with the substation of any called subscriber, including means having vertical motion to select groups and rotary motion to connect with a line in the selected group, and subscriber-controlled automatic means for producing an audible call-signal at the substation of any called subscriber.

73. A telephone system comprising a subscriber's substation relay provided with an armature, a switch-hook provided with means for controlling said armature, a condenser connected in parallel with the coil of said relay, subscriber-controlled switching machinery at the exchange or central station, adapted for use by calling subscribers in automatically establishing connection with the lines of the called subscribers, including means having vertical motion to select groups and rotary motion to connect with a line in the selected group, and line circuits for controlling said switching machinery, said line circuits controlled by said relay, substantially as and for the purpose set forth.

74. A subscriber's substation relay, a substation transmitter, a plurality of energizing circuits for said relay, each circuit including said transmitter, subscriber-controlled switching machinery at the exchange or central station, adapted for use by calling subscribers in automatically establishing connection with the lines of the called subscribers, including means having vertical motion to select groups and rotary motion to connect with a line in the selected group, and line circuits for controlling said switching machinery, said line circuits controlled by said relay, substantially as and for the purpose set forth.

75. In a telephone system, the combination of subscriber-controlled automatic switching means for establishing connection with the substation of any called subscriber, including means having vertical motion to select groups and rotary motion to connect with a line in the selected group, a line circuit, a centralized source of switching and talking current, a couple of microphone transmitters temporarily connected in parallel in said circuits, a third transmitter temporarily connected in parallel with the other transmitters, and a subscriber's substation relay allotted to the said third transmitter and having its coil temporarily connected in series therewith.

76. A telephone system comprising a party-line, a plurality of substations on said line, a normally hung up receiver at each

- substation, a relay at each substation, subscriber-controlled automatic means for establishing connection with the substation of any called subscriber, including means having vertical motion to select groups and rotary motion to connect with a line in the selected group, circuits controlled by said relays, and means whereby the taking down of any receiver will energize the relay of the same substation if any other receiver on the same line is down. 65
77. A telephone system comprising a party-line, a plurality of substations thereon, subscriber-controlled automatic means for establishing connection with the substation of any called subscriber, including means having vertical motion to select groups and rotary motion to connect with a line in the selected group, a lock-out relay at each substation, a normally hung up receiver at each substation, circuits controlled by said relays, a plurality of energizing circuits for each relay, and means co-operating with said relays to give any subscriber on the line exclusive possession thereof for switching purposes as soon as he takes down his receiver, the different energizing circuits of each relay extending through the different substations. 70
78. A telephone system comprising a party-line, a plurality of substations on said line, subscriber-controlled automatic means for establishing connection with the substation of any called subscriber, including means having vertical motion to select groups and rotary motion to connect with a line in the selected group, a lock-out relay at each substation, and a plurality of energizing circuits for each relay, each of said energizing circuits including the two sides of the said line in parallel. 75
79. A telephone system comprising a party-line, a plurality of substations thereon, subscriber-controlled automatic switching means for establishing connection with the substation of any called subscriber, including means having vertical motion to select groups and rotary motion to connect with a line in the selected group, a centralized source of switching and talking current, a lock-out relay at each substation, and an energizing circuit for each relay, each of said energizing circuits including the two sides of the said line in parallel. 80
80. A telephone system comprising a party-line, a plurality of substations on said line, subscriber-controlled automatic means for establishing connection with the substations of any called subscriber, including means having vertical motion to select groups and rotary motion to connect with a line in the selected group, a relay at each substation, a ground connection located at each substation and controlled by the relay thereof, and a plurality of energizing circuits for each relay, one or more of said energizing circuits including the two sides of the line in parallel. 85
81. A telephone system comprising a party-line, a plurality of substations on said line, subscriber-controlled automatic switching means for establishing connection with the substation of any called subscriber, including means having vertical motion to select groups and rotary motion to connect with a line in the selected group, a relay at each substation, a ground connection located at each substation and controlled by the relay thereof, a plurality of energizing circuits for each relay, one or more of said energizing circuits including the two sides of the line in parallel, and a centralized source of switching and talking current. 90
82. A telephone system comprising a party-line, a plurality of substations thereon, lock-out means at each substation, a plurality of talking circuits for each substation, subscriber-controlled automatic switching means for establishing connection with any called subscriber, including means having vertical motion to select groups and rotary motion to connect with a line in the selected group, and a centralized source of switching and talking current, one talking circuit being closed when the subscriber is in possession of the line for switching purposes, the other talking circuit being closed when the subscriber is locked out by reason of the line being in the possession of some other subscriber. 95
83. A telephone system comprising a party-line, a plurality of substations thereon, subscriber-controlled automatic means for establishing connection with the substation of any called subscriber, including means having vertical motion to select groups and rotary motion to connect with a line in the selected group, a relay at each substation, a transmitter at each substation, and a plurality of energizing circuits for each relay, the energizing circuits of any relay each including the transmitter of a different substation. 100
84. A telephone system comprising a party-line, a plurality of substations thereon, subscriber-controlled automatic switching means for establishing connection with the substation of any called subscriber, including means having vertical motion to select groups and rotary motion to connect with a line in the selected group, a relay at each substation, a transmitter at each substation, a plurality of energizing circuits for each relay, the energizing circuits of any relay each including the transmitter of a different substation, and a centralized source of switching and talking current. 105
85. A telephone system comprising a

- party-line, a plurality of substations thereon, a lock-out relay at each substation, a hook-switch at each substation, and an energizing circuit for each relay, such energizing circuit being provided with two switch points controlled by the hook-switch of the same substation, subscriber-controlled automatic switching means for establishing connection with the substation of any called subscriber, including means having vertical motion to select groups and rotary motion to connect with a line in the selected group, and a centralized source of switching and talking current.
86. A telephone system comprising a party-line, a plurality of substations thereon, a lock-out relay at each substation, a hook-switch at each substation, an energizing circuit for each relay, each energizing circuit being provided with two normally open switch points controlled by the hook-switch of the same substation, subscriber-controlled automatic switching means for establishing connection with the substation of any called subscriber, including means having vertical motion to select groups and rotary motion to connect with a line in the selected group, and a centralized source of switching and talking current.
87. A telephone system comprising lines, a party-line, a plurality of substations thereon, subscriber-controlled automatic switching means for establishing connection with the line of any called subscriber, controllable from any substation on the party-line, including means having vertical motion to select groups and rotary motion to connect with a line in the selected group, a transmitter at each substation, a hook-switch at each substation, a receiver normally resting upon each hook-switch, a centralized source of switching and talking current, and a circuit for each transmitter, each transmitter-circuit having two normally open switch points controlled by the hook-switch of the same substation.
88. A telephone system comprising a party-line, a plurality of substations thereon, subscriber-controlled automatic switching means for establishing connection with the substation of any called subscriber, including means having vertical motion to select groups and rotary motion to connect with a line in the selected group, a transmitter at each substation, a hook-switch at each substation, a receiver normally resting upon each hook-switch, a centralized source of switching and talking current, a circuit for each transmitter, and substation lock-out relays provided with energizing circuits controlled by themselves and by the hook-switches, each transmitter-circuit having two normally open switch points controlled by the hook-switch of the same substation.
89. A telephone system comprising a
- party-line, a plurality of substations thereon, subscriber-controlled automatic switching means for establishing connection with the substation of any called subscriber, including means having vertical motion to select groups and rotary motion to connect with a line in the selected group, a transmitter at each substation, a receiver normally resting upon each hook-switch, a centralized source of switching and talking current, and a circuit for each transmitter, each transmitter-circuit having two normally open switch points controlled by the hook-switch of the same substation, the said subscriber-controlled means having vertical motion to select groups and rotary motion to connect with a line in the selected group, a transmitter at each substation, a receiver normally resting upon each hook-switch, a centralized source of switching and talking current, and a circuit for each transmitter, each transmitter-circuit having two normally open switch points controlled by the hook-switch of the same substation, the said subscriber-controlled means comprising a connector provided with a differential relay, a switch releasing circuit controlled by said differential relay, and a pole-changing relay adapted when energized to switch the source of current in series between the windings of said differential relay.
90. A telephone system comprising a party-line, a plurality of substations thereon, subscriber-controlled automatic switching means for establishing connection with the substation of any called subscriber, including means having vertical motion to select groups and rotary motion to connect with a line in the selected group, a transmitter at each substation, a receiver normally resting upon each hook-switch, a centralized source of switching and talking current, and a circuit for each transmitter, and substation lock-out relays provided with energizing circuits controlled by themselves and by the hook-switches, each transmitter-circuit having two normally open switch points controlled by the hook-switch of the same substation, the said subscriber-controlled means comprising a connector provided with a differential relay, a switch releasing circuit controlled by said differential relay, and a pole-changing relay adapted when energized to switch the source of current in series between the windings of said differential relay.
91. A telephone system comprising a party-line, a plurality of substations thereon, subscriber-controlled automatic switching means for establishing connection with the substation of any called subscriber, including means having vertical motion to select groups and rotary motion to connect with a line in the selected group, a switch-hook at each substation, a lock-out relay at each substation, connections for short-circuiting or shunting each relay as soon as its allotted switch-hook is raised, and a centralized source of switching and talking current.
92. A telephone system comprising a subscriber's station, subscriber-controlled automatic switching means for establishing connection with the substation of any called subscriber, including means having vertical motion to select groups and rotary motion to

connect with a line in the selected group, a substation relay, a subscriber's switch-hook, a centralized source of switching and talking current, and means whereby the said relay is short-circuited or shunted when the switch-hook is permitted to rise.

93. A telephone system comprising a subscriber's line, a plurality of substations on said line, subscriber-controlled automatic switching means for establishing connection between any two of said substations, or between any one of said substations and any other substation in the system, including means having vertical motion to select 15 groups and rotary motion to connect with a line in the selected group, a centralized source of talking and switching current, relays located at said substations, and suitable circuits and subscriber-operated devices 20 whereby said relays are operative to prevent any subscriber on the said line from using the latter when the same is already in use between other subscribers, the said subscriber-controlled means comprising a connector 25 provided with a differential relay, a switch releasing circuit controlled by said differential relay, and a pole-changing relay adapted when energized to switch the source of current in series between the windings of 30 said differential relay.

94. In a telephone system, the combination of a party-line, a plurality of substations on said line, subscriber-controlled automatic switching means for establishing 35 connection between any two of said substations, or between one of said substations and any other substation of the system, including means having vertical motion to select groups and rotary motion to connect with a 40 line in the selected group, microphone transmitters at the said substations, a centralized source of switching current adapted also for supplying talking current to said transmitters, and automatic electromagnetic 45 means operated by current from said source of supply and adapted to prevent any subscriber on the said line from making use thereof when the same is already in service between other subscribers, the said subscriber-controlled means comprising a connector 50 provided with a differential relay, a switch releasing circuit controlled by said differential relay, and a pole-changing relay adapted when energized to switch the 55 source of current in series between the windings of said differential relay.

95. An automatic telephone system comprising a subscriber's microphone transmitter, a centralized source of talking current, 60 a line circuit including said transmitter and source of current in series, a subscriber's relay controlling the line circuit extending through, said transmitter, and subscriber-controlled automatic switching means for establishing connection with the substation 65

of any called subscriber, including means having vertical motion to select groups and rotary motion to connect with a line in the selected group, the said subscriber-controlled means comprising a connector provided with a differential relay, a switch releasing circuit controlled by said differential relay, and a pole-changing relay adapted when energized to switch the source of current in series between the windings of 70 75 said differential relay.

96. An automatic telephone system comprising a line circuit, a microphone transmitter in said circuit, a ringing key in said circuit, a relay associated with and controlling the flow of current through said transmitter and ringing key, a centralized source of switching and talking current, and subscriber-controlled automatic switching 80 means for establishing connection with the 85 substation of any called subscriber, including means having vertical motion to select groups and rotary motion to connect with a line in the selected group, the said subscriber-controlled means comprising a connector provided with a differential relay, a switch releasing circuit controlled by said differential relay, and a pole-changing relay adapted when energized to switch the 90 source of current in series between the 95 windings of said differential relay.

97. An automatic telephone system comprising a ground circuit, a substation, a microphone transmitter at the substation, a normal line circuit for said transmitter, a 100 relay located at the substation and controlling both of said circuits, a centralized source of switching and talking current, and subscriber-controlled automatic switching 105 means for establishing connection with the 110 substation of any called subscriber, including means having vertical motion to select groups and rotary motion to connect with a line in the selected group, the said subscriber-controlled means comprising a connector provided with a differential relay, a switch releasing circuit controlled by said differential relay, and a pole-changing relay adapted when energized to switch the 115 source of current in series between the windings of said differential relay.

98. In a telephone system, the combination of subscriber-controlled automatic switching means for establishing connection with the substation of any called subscriber, 120 including means having vertical motion to select groups and rotary motion to connect with a line in the selected group, a line circuit, a centralized source of switching and talking current, a couple of microphone 125 transmitters temporarily connected in parallel in said circuit, a third transmitter temporarily connected in parallel with the other transmitters, and a subscriber's substation relay allotted to the said third transmitter 130

- and having its coil temporarily connected in series therewith, the said subscriber-controlled means comprising a connector provided with a differential relay, a switch releasing circuit controlled by said differential relay, and a pole-changing relay adapted when energized to switch the source of current in series between the windings of said differential relay.
- 10 99. A telephone system comprising a party-line, a plurality of substations thereon, subscriber-controlled automatic switching means for establishing connection with the substation of any called subscriber, including means having vertical motion to select groups and rotary motion to connect with a line in the selected group, a centralized source of switching and talking current, a lock-out relay at each substation, and an energizing circuit for each relay, each of said energizing circuits including the two sides of the said line in parallel, the said subscriber-controlled means comprising a connector provided with a differential relay, a switch releasing circuit controlled by said differential relay, and a pole-changing relay adapted when energized to switch the source of current in series between the windings of said differential relay.
- 15 100. A telephone system comprising a party-line, a plurality of substations thereon, lock-out means at each substation, a plurality of talking circuits for each substation, subscriber-controlled automatic switching means for establishing connection with any called subscriber, including means having vertical motion to select groups and rotary motion to connect with a line in the selected group, and a centralized source of switching and talking current, one talking circuit being closed when the subscriber is in possession of the line for switching purposes, the other talking circuit being closed when the subscriber is locked out by reason of the line being in the possession of some other subscriber, the said subscriber-controlled means comprising a connector provided with a differential relay, a switch releasing circuit controlled by said differential relay, and a pole-changing relay adapted when energized to switch the source of current in series between the windings of said differential relay.
- 20 101. A telephone system comprising a party-line, a plurality of substations thereon, subscriber-controlled automatic switching means for establishing connection with the substation of any called subscriber, including means having vertical motion to select groups and rotary motion to connect with a line in the selected group, a relay at each substation, a transmitter at each substation, a plurality of energizing circuits for each relay, the energizing circuits of any relay each including the transmitter of a different
- 25 substation, and a centralized source of switching and talking current, the said subscriber-controlled means comprising a connector provided with a differential relay, a switch releasing circuit controlled by said differential relay, and a pole-changing relay adapted when energized to switch the source of current in series between the windings of said differential relay.
- 30 102. A telephone system comprising a party-line, a plurality of substations thereon, a lock-out relay at each substation, a hook-switch at each substation, an energizing circuit for each relay, each energizing circuit being provided with two switch points controlled by the hook-switch of the same substation, subscriber-controlled automatic switching means for establishing connection with the substation of any called subscriber, including means having vertical motion to select groups and rotary motion to connect with a line in the selected group, and a centralized source of switching and talking current, the said subscriber-controlled means comprising a connector provided with a differential relay, a switch releasing circuit controlled by said differential relay, and a pole-changing relay adapted when energized to switch the source of current in series between the windings of said differential relay.
- 35 103. A telephone exchange system comprising lines, a party-line, a plurality of substation common battery transmitters bridged across the said party-line, subscriber-controlled automatic switching means for establishing connection with the substation of any called subscriber, controllable from any substation on the party-line, including means having vertical motion to select groups and rotary motion to connect with a line in the selected group, subscriber-controlled means for producing an audible call-signal at any called substation on the said party-line, and a common battery or centralized source of switching and talking current.
- 40 104. A telephone exchange system comprising a party-line, a plurality of substation common battery transmitters connected with the said line, subscriber-controlled automatic switching means for establishing connection with the substation of any transmitter on said line, or with other substations in the same exchange, controllable from any substation on the party-line, including means having vertical motion to select groups and rotary motion to connect with a line in the selected group, and a common battery or centralized source of switching and talking current.
- 45 105. In a telephone system, a party-line, a common battery for talking purposes, automatic means by which a calling subscriber establishes communication with the called subscriber, including means having vertical

- motion to select groups and rotary motion to connect with a line in the selected group, and automatic means for preventing the subscribers on the said line interfering with an established connection.
106. In a telephone system, a party-line, a common battery for talking purposes, automatic means for trunking between subscribers, including means having vertical motion to select groups and rotary motion to connect with a line in the selected group, and automatic means for preventing the subscribers on said line interfering with an established connection.
107. In a telephone system, a party-line, a common battery for talking purposes, automatic means by which a calling subscriber establishes communication with the called subscriber, including means having vertical motion to select groups and rotary motion to connect with a line in the selected group, and automatic means for preventing the subscribers on the said line interfering with an established connection, both of said means operated by current from said battery.
108. In a telephone system, a party-line, a common battery for talking purposes, automatic means for trunking between subscribers, including means having vertical motion to select groups and rotary motion to connect with a line in the selected group, and automatic means including relays at the different substations for preventing the subscribers on said line interfering with an established connection.
109. A telephone system comprising a line, a group of substations for said line, a common battery for talking purposes; automatic means for extending connection from said line, including means having vertical motion to select groups and rotary motion to connect with a line in the selected group, and automatic means for locking out all other substations of the group when one substation thereof is using the said line, so as to prevent interference with an established connection.
110. A telephone system comprising a line, a group of substations to which said line is common, automatic means for trunking said line into connection with a suitable part of the system, including means having vertical motion to select groups and rotary motion to connect with a line in the selected group, a common battery for talking purposes, and automatic means for locking out all other substations in the group when one substation thereof is using the line, so as to prevent interference with an established connection.
111. In a telephone system, a party-line, a common battery for talking purposes, automatic means for trunking between subscribers, including means having vertical motion to select groups and rotary motion to connect with a line in the selected group, and automatic means including relays at the different substations for preventing the subscribers on said line interfering with an established connection, both of said automatic means operated by current from said battery or common source of talking current.
112. A telephone system comprising a line, a group of substations for said line, a common battery for talking purposes, automatic means for extending connection from said line, including means having vertical motion to select groups and rotary motion to connect with a line in the selected group, and automatic means for locking out all other substations of the group when one substation thereof is using the said line so as to prevent interference with an established connection, both of said automatic means operated by current from said battery or common source of talking current.
113. A telephone system comprising a line, a group of substations to which said line is common, automatic means for trunking said line into connection with a suitable part of the system, including means having vertical motion to select groups and rotary motion to connect with a line in the selected group, a common battery for talking purposes, and automatic means for locking out all other substations in the group when one substation thereof is using the line, so as to prevent interference with an established connection, both of said automatic means operated by current from said battery or common source of talking current.
114. In a telephone system, the combination of lines, automatic trunking machinery including means having vertical motion to select groups and rotary motion to connect with a line in the selected group, a common battery for talking purposes, and for operating said machinery, automatic means for partially preventing interference between subscribers on the same line in the use of said trunking machinery, and means by which the subscribers control the flow of current in the lines for both operating and talking purposes.
115. In a telephone system, lines arranged in groups, automatic trunking means including means having vertical motion to select groups and rotary motion to connect with a line in the selected group, a series of relays for preventing the subscribers on a party-line interfering with an established connection, circuits directly controlled by said relays, and a common battery for talking purposes, and for operating the automatic trunking means.
116. In a telephone system, the combina-

tion of a subscriber's line, a plurality of substations thereon, a connector provided with a differential relay, a centralized source of current for supplying current through the coils of said relay to the said line for talking purposes, a local release circuit controlled by said differential relay, subscribers' transmitters located at said substations and receiving talking current from said source of current supply, subscriber-operated means at each substation for controlling the operations of said connector, and automatic means located at the said substations and adapted to prevent seizure of the line for operating purposes by any subscriber thereon when the same is already in service between other subscribers, said connector provided with means having vertical motion to select groups and rotary motion to connect with the called line in the selected group.

117. An automatic telephone system comprising a party-line, a plurality of substations on said line, lock-out relays at said substations, means whereby said relays are operative to prevent seizure of the line by any subscriber thereon when the same is already in service between other subscribers, microphones transmitters at said substations, switches having vertical motion to select groups and rotary motion to connect with a line in the selected group, a centralized source of switching and talking current, and a plurality of energizing circuits for each relay, one of the energizing circuits of each relay including the transmitter of the same substation.

118. An automatic telephone system comprising lines arranged in groups, a subscriber's substation relay, ground and metallic circuits controlled by said relay, a subscriber's substation microphone transmitter, switches having vertical motion to select groups and rotary motion to connect with a line in the selected group, a centralized source of switching and talking current, and an energizing circuit for said relay including said transmitter, said relay controlling the use of said switches.

119. An automatic telephone system comprising trunks arranged in groups, a switch comprising a shaft, a pair of shaft line wipers, a side switch having a pair of line wipers, a pair of private normal relays having coils connecting the shaft wipers with the side switch wipers, said coils thereby constituting part of the main trunk line circuit, and a private normal provided with normally open and normally closed switch points connected in parallel and controlled by said private normal relays, said switch having vertical motion to select groups and rotary motion to automatically select an idle trunk in the selected group.

120. An automatic telephone system comprising trunks arranged in groups, a subscriber's substation relay, a connector pole-changing relay, trunking switches having vertical motion to select groups and rotary motion to automatically select an idle trunk in the selected group, a centralized source of talking and switching current, a switch to be shifted from one pole of the battery to the other by said pole-changing relay, a subscriber's substation transmitter, and a circuit by which the substation relay is energized in multiple or parallel with the connector pole-changing relay, whereby the current is supplied to the transmitter through the said relay, said relay controlling the use of said switches.

121. An automatic telephone system comprising a subscriber's substation relay, a line circuit, trunking switches having vertical motion to select groups and rotary motion to automatically select an idle trunk in the selected group, a centralized source of switching and talking current, a plurality of subscribers' microphone transmitters connected with the said line circuit, and an energizing circuit for said relay including said transmitters in multiple, said relay controlling the use of said switches.

122. An automatic telephone system comprising a connector having a differential relay provided with a pair of normally open switch springs, a release circuit controlled by said switch springs, a pair of normally closed switch springs, a pole-changing relay, a circuit for said pole-changing relay controlled by said normally closed switch springs, trunking switches having vertical motion to select groups and rotary motion to automatically select an idle trunk in the selected group, a centralized source of switching and talking current, and an operating circuit to be switched by said pole-changing relay from one pole of said source of current to the other, said relay controlling the use of said switches.

123. A telephone system comprising a party-line, a plurality of substations on said line, a normally hung up receiver at each substation, a relay at each substation, a ground connection located at each substation and controlled by the relay thereof, trunking switches having vertical motion to select groups and rotary motion to automatically select an idle trunk in the selected group, and means whereby the taking down of any receiver will energize its allotted relay if the receiver is already down at some other substation on the same line, said relay controlling the use of said switches.

124. A telephone system comprising a party-line, a plurality of substations on said line, a relay at each substation, circuits controlled by said relays, normally hung up

- receivers at each of said substations, trunking switches having vertical motion to select groups and rotary motion to automatically select an idle trunk in the selected group, and means whereby any one of said relays is energizable by the taking down of its allotted receiver as soon as any other receiver is down at some other substation on the same line, said relay controlling the use of said switches. 10
125. A telephone system comprising a calling subscriber's line, a connector provided with a pole-changing relay, a battery, an operating circuit to be switched by said pole-changing relay from one pole of said battery to the other, calling and called subscribers' stations connected together by the said calling line, trunking switches having vertical motion to select groups and rotary motion to automatically select an idle trunk in the selected group, and an energizing circuit for said relay including both sides of the said line, said relay controlling the use of said switches. 15
126. A telephone system comprising a calling subscriber's line, a connector provided with a pole-changing relay, a battery, an operating circuit to be switched by said relay from one pole of said battery to the other, trunking switches having vertical motion to select groups and rotary motion to automatically select an idle trunk in the selected group, and an energizing circuit for said relay including both sides of the said calling line, said relay controlling the use of said switches. 20
127. A telephone system comprising a party-line, a plurality of substations thereon, lock-out means at each substation, trunking switches having vertical motion to select groups and rotary motion to automatically select an idle trunk in the selected group, and a plurality of talking circuits for each substation, one talking circuit being closed when the subscriber is in possession of the line for switching purposes, the other talking circuit being closed when the subscriber is locked out by reason of the line being in the possession of some other subscriber, said relay controlling the use of said switches. 25
128. A telephone system comprising a party-line, a plurality of substations thereon, a lock-out relay at each substation, a hook-switch at each substation, trunking switches having vertical motion to select groups and rotary motion to automatically select an idle trunk in the selected group, and an energizing circuit for each relay, each energizing circuit being provided with two normally open switch points controlled by the hook-switch of the same substation, said relay controlling the use of said switches. 30
129. A telephone system comprising a party-line, a plurality of substations on said line, subscriber-controlled automatic switching means for establishing connection with the substation of any called subscriber, including means having vertical motion to select groups and rotary motion to connect with the called line in the selected group, a relay at each substation, a ground connection located at each substation and controlled by the relay thereof, a plurality of energizing circuits for each relay, one or more of said energizing circuits including the two sides of the line in parallel, and a centralized source of switching and talking current, the said subscriber-controlled means comprising a connector provided with a differential relay, a switch releasing circuit controlled by said differential relay, and a pole-changing relay adapted when energized to switch the source of current in series between the windings of said differential relay. 35
130. A telephone system comprising a calling subscriber's line, a connector temporarily set on said line to give connection with another substation on the same line, including means having vertical motion to select groups and rotary motion to connect with the called line in the selected group, a centralized source of switching and talking current, said connector having a pair of voice-current conductors normally both connected in parallel with the same pole of the said source of current, a pole-changing relay temporarily energized to switch the source of current in series between the said voice-current conductors, and an energizing circuit for said relay including the substation of the calling subscriber. 40
131. In a telephone system, a party-line, a common battery for talking purposes, automatic means for trunking between subscribers, including means having vertical motion to select groups and rotary motion to connect with a line in the selected group, and automatic means for preventing the subscribers on said line interfering with an established connection, both of said means operated by current from said battery. 45
132. In a telephone system, a party-line having a plurality of substations thereon, a relay at each of said substations controlled by the switch-hooks thereof and having independent energizing circuits, and a condenser permanently connected in shunt of each of said relays, said relays each controlling the operating ground circuit. 50
133. In a telephone system, a party-line having a plurality of substations, a relay at each of said substations, and a condenser in shunt of each of said relays, each of said relays controlling the operating ground circuit. 55
134. The combination of a plurality of

party line substations, lock-out devices for the party-line substations, a common battery for supplying talking current to the party line substations, an automatic individual switch allotted to the party line substations, a plurality of automatic switches, and trunk lines leading from the individual switch to the automatic switches.

135. The combination of a plurality of 10 party line substations, lock-out devices for the party line substations, a common battery for supplying talking current to the party line substations, an automatic individual switch allotted to the party line substations, 15 connecting apparatus, and trunk lines leading from the individual switch to the connecting apparatus.

136. In a system in which the lines are 20 divided into groups, the combination of a plurality of party line substations, lock-out devices for the party line substations, a common battery for supplying talking current to the party line substations, an individual switch allotted to the party line substations, a plurality of automatic switches, 25 each automatic switch having vertical motion to select groups and rotary motion to find a line in any selected group, and trunk lines leading from the individual switches to 30 the automatic switches.

137. In a system in which the trunks and 35 subscribers' lines are divided into groups, the combination of a plurality of party line substations, lock-out devices for the party line substations, a common battery for supplying talking current to the party line substations, an automatic individual switch allotted to the party line, connecting apparatus, and trunk lines leading from the individual switch to the connecting apparatus, 40 said connecting apparatus having vertical motion to find groups and rotary motion to find idle trunks and called lines.

138. In a telephone system, a telephone 45 line, a plurality of substations for said line, a lock-out relay for each telephone for preventing one telephone from interfering with another, a separate energizing circuit for each relay, an operating circuit for each telephone, the lock-out relay of each telephone 50 controlling the operating circuit of its telephone, a common battery for supplying talking current to the substations on said line, and a switch associated with the line controlling the circuits of all the lockout relays

139. In a telephone system, a telephone line, a plurality of sub-stations for said line, a lock-out relay for each telephone for preventing one telephone from interfering with another, a common battery for supplying talking current to the substations on said line, a switch associated with said line controlling the energizing circuits of said relays, and means at each telephone for oper-

ating said switch to prepare an energizing 65 circuit for a plurality of said relays.

140. In a telephone system, a telephone line, a plurality of sub-stations for said line, a lock-out relay for each telephone for preventing one telephone from interfering with another, a separate energizing circuit in each telephone for each lock-out relay, means controlled at each telephone for rendering the relay of said telephone inoperative during a call and for permitting any one of the 75 other relays to be operated during the same call, a common battery for supplying talking current to the substations on said line, and a switch associated with said line for controlling the energizing circuits of said 80 relays.

141. In a telephone system, a line, a plurality of telephones for said line, a lock-out mechanism for each telephone for preventing the interference of its telephone with 85 any other telephone that is calling, each of said lock-outs being normally inoperative, whereby when a telephone is operated its lock-out does not operate, means controlled when the telephone receiver is removed to 90 render the lock-out mechanisms operable whereby when any other telephone is operated its lock-out is operated, and a common battery for supplying talking current to the 95 telephones on said line.

142. In a telephone system, a line, an automatic switch for said line, a plurality of telephones for said line, an impulse sender for each telephone for operating said switch over said line, an electromagnetic lock-out 100 mechanism for each telephone for rendering its impulse sender inoperable, and a common battery for supplying talking current to the 105 telephones on said line.

143. In a telephone system, a line, an automatic switch for said line, a plurality of telephones for said line, an impulse sender for each telephone for operating said switch over said line, an electromagnetic lock-out 110 mechanism for each telephone for rendering its impulse sender inoperable after any other telephone on the line is operated, and a common battery for supplying talking current to the 115 telephones on said line.

144. In a telephone system, a line, an automatic switch for said line, a plurality of telephones for said line, an impulse sender for each telephone for operating said switch over said line, an electromagnetic lock-out 120 mechanism for each telephone for rendering its impulse sender inoperable only after another telephone is operated, and a common battery for supplying talking current to the 125 telephones on said line.

145. In a telephone system, a line, an automatic switch for said line, a plurality of telephones for said line, an impulse sender for each telephone for operating said switch

- over said line, an electromagnetic lock-out device for each telephone, a circuit for each lock-out controlled by the switch, each lock-out when operated rendering the impulse 5 sender of its telephone inoperative, and a common battery for supplying talking current to the telephones on said line.
146. In a telephone system, a line, an automatic switch for said line, a plurality of 10 telephones for said line, an impulse sender for each telephone for operating said switch over said line, an electromagnetic lock-out device for each telephone, a circuit for each lock-out controlled by the switch, each lock- 15 out when operated rendering the impulse sender of its telephone inoperative after any other telephone has operated the switch, and a common battery for supplying talking current to the telephones on said line.
147. In a telephone system, a line, an automatic switch for said line, a plurality of 20 telephones for said line, an impulse sender for each telephone for operating said switch over said line, an electromagnetic lock-out device for each telephone, a circuit for each lock-out controlled by the switch, each lock- 25 out when operated rendering the impulse sender of its telephone inoperative only after any other telephone has operated the switch, 30 and a common battery for supplying talking current to the telephones on said line.
148. In a telephone system, a line, an automatic switch for said line, a plurality of 35 telephones for said line, an impulse sender for each telephone for operating said switch over said line, an electromagnetic lock-out device for each telephone, a circuit for each lock-out controlled by the switch and the 40 telephone, and a common battery for supplying talking current to the telephones on said line.
149. In a telephone system, a line, an automatic switch for said line, a plurality of 45 telephones for said line, an impulse sender for each telephone for operating said switch over said line, an electromagnetic lock-out device for each telephone, a circuit for each lock-out controlled by the switch and the 50 telephone only after another telephone has operated the switch, and a common battery for supplying talking current to the telephones on said line.
150. In a telephone system, a line, an automatic switch for said line, a plurality of 55 telephones for said line, an impulse sender for each telephone for operating said switch over said line, an electromagnetic lock-out mechanism for each telephone for rendering its impulse sender inoperative, a normally 60 inoperative circuit common to all said lock-out devices controlled by said switch and rendered operative when the switch is operated, an individual branch for each lock-out controlled by its associated telephone to 65 operate the lock-out after the switch has operated, and a common battery for supplying talking current to the telephones on said line.
151. In a telephone system, a line, an automatic switch for said line, a plurality of 70 telephones for said line, an impulse sender for each telephone for operating said switch over said line, an electromagnetic lock-out mechanism for each telephone for rendering its impulse sender inoperative, a normally 75 open circuit common to all said lock-out devices controlled by said switch to close the same when the switch is operated, an individual branch for each lock-out controlled by its associated telephone to operate the lock-out after the switch has closed the circuit, and a common battery for supplying talking current to the telephones on said line.
152. In a telephone system, a line, an automatic switch for said line, a plurality of 80 telephones for said line, an impulse sender for each telephone for operating said switch over said line, an electromagnetic lock-out mechanism for each telephone for rendering its impulse sender inoperative, a normally 85 open circuit common to all said lock-out devices controlled by said switch to close the same when the switch is operated, a normally open individual branch for each lock-out mechanism controlled by its associated telephone to close an energizing circuit for the lock-out mechanism after the switch is 90 operated, and a common battery for supplying talking current to the telephones on said line.
153. In a telephone system, a line, an automatic switch for said line, a plurality of 95 telephones for said line, an impulse sender for each telephone for operating said switch over said line, an electromagnetic lock-out mechanism for each telephone for rendering its impulse sender inoperative, a normally 100 inoperative circuit common to all said lock-out devices controlled by said switch and rendered operative when the switch is operated, an individual branch for each lock-out controlled by its associated telephone to operate the lock-out after the switch has 105 operated, said common circuit comprising the line, and a common battery for supplying talking current to the telephones on said line.
154. In a telephone system, a line, an automatic switch for said line, a plurality of 110 telephones for said line, an impulse sender for each telephone for operating said switch over said line, an electromagnetic lock-out mechanism for each telephone for rendering its impulse sender inoperative, a normally 115 open circuit common to all said lock-out devices controlled by said switch to close the same when the switch is operated, an

individual branch for each lock-out controlled by its associated telephone to operate the lock-out after the switch has closed the circuit, said common circuit comprising 5 the line, and a common battery for supplying talking current to the telephones on said line.

155. In a telephone system, a line, an automatic switch for said line, a plurality of 10 telephones for said line, an impulse sender for each telephone for operating said switch over said line, an electromagnetic lock-out mechanism for each telephone for rendering its impulse sender inoperable, a normally 15 open circuit common to all said lock-out devices controlled by said switch to close the same when the switch is operated, a normally open individual branch for each lock-out mechanism controlled by its associated 20 telephone to close an energizing circuit for the lock-out mechanism after the switch is operated, said common circuit comprising the line, and a common battery for supplying talking current to the telephones on said line.

156. In a telephone system, a line, an automatic switch for said line, a plurality of telephones for said line, an impulse sender for each telephone for operating said switch 30 over said line, an electromagnetic lock-out mechanism for each telephone for rendering its impulse sender inoperable, a normally inoperative circuit common to all said lock-out devices controlled by said switch and rendered operative when the switch is operated, an individual branch for each lock-out controlled by its associated telephone to operate the lock-out after the switch has operated, said common circuit comprising only one 35 side of the line, and a common battery for supplying talking current to the telephones on said line.

157. In a telephone system, a line, an automatic switch for said line, a plurality of 45 telephones for said line, an impulse sender for each telephone for operating said switch over said line, an electromagnetic lock-out mechanism for each telephone for rendering its impulse sender inoperable, a normally 50 open circuit common to all said lock-out devices controlled by said switch to close the same when the switch is operated, an individual branch for each lock-out controlled by its associated telephone to operate the 55 lock-out after the switch has closed the circuit, said common circuit comprising only one side of the line, and a common battery for supplying talking current to the telephones on said line.

60 158. In a telephone system, a line, an automatic switch for said line, a plurality of telephones for said line, an impulse sender for each telephone for operating said switch over said line, an electromagnetic lock-out

mechanism for each telephone for rendering 65 its impulse sender inoperable, a normally open circuit common to all said lock-out devices controlled by said switch to close the same when the switch is operated, a normally open individual branch for each lock-out mechanism controlled by its associated telephone to close an energizing circuit for the lock-out mechanism after the switch is operated, said common circuit comprising only one side of the line, and a common battery 70 for supplying talking current to the telephones on said lines.

159. In a telephone system, a line, an automatic switch for said line, a plurality of 75 telephones for said line, an impulse sender for each telephone for operating said switch over said line, an electromagnetic lock-out mechanism for each telephone for rendering its impulse sender inoperable, a circuit common to all of said lock-out mechanisms controlled by said switch, an individual branch 80 for each lock-out mechanism controlled by its associated telephone, and a common battery for supplying talking current to the telephones on said line.

160. In a telephone system, a line, an automatic switch for said line, a plurality of 85 telephones for said line, an impulse sender for each telephone for operating said switch over said line, an electromagnetic lock-out 90 mechanism for each telephone for rendering its impulse sender inoperable, a circuit common to all of said lock-out mechanisms controlled by said switch, an individual branch for each lock-out mechanism controlled by 95 its associated telephone, said common circuit individual to the line, and a common battery for supplying talking current to the telephones on said line.

161. In a telephone system, a line, an automatic switch for said line, a plurality of 100 telephones for said line, an impulse sender for each telephone for operating said switch over said line, an electromagnetic lock-out 105 mechanism for each telephone for rendering its impulse sender inoperable, a circuit common to all of said lock-out mechanisms controlled by said switch, an individual branch for each lockout mechanism controlled by its 110 associated telephone, said common circuit individual to one side of the line, and a common battery for supplying talking current 115 to the telephones on said line.

162. In a telephone system, a line, an automatic switch for said line, a plurality of 120 telephones for said line, an impulse sender for each telephone for operating the switch over said line, an electromagnetic lock-out mechanism for each telephone, for rendering its impulse sender inoperable, a circuit common to all of said lock-out mechanisms controlled by said switch, an individual branch circuit for each lock-out mechanism con- 125

trolled by its telephone whereby when the first telephone comes on the line to operate the switch its lock-out does not operate, and whereby the other lock-out devices are rendered operable when any other telephone is brought on the line, whereby said other telephone is prevented from interfering, if its impulse mechanism is operated, with the connection of the telephone previously on

the line, and a common battery for supplying talking current to the telephones on said line.

Signed by me at Chicago, Cook county, Illinois, this 30th day of January, 1906.

TALBOT G. MARTIN.

J. MEYER.

Copies of this patent may be obtained for five cents each, by addressing the "Commissioner of Patents,
Washington, D. C."

It is hereby certified that in Letters Patent No. 1,151,546, granted August 24, 1915, upon the application of Talbot G. Martin, of Chicago, Illinois, for an improvement in "Automatic Common-Battery Party-Line Telephone Systems," errors appear in the printed specification requiring correction as follows: Page 4, line 121, for the compound word "private-maget" read *private-magnet*; page 5, line 39, for "wipers" read *wiper*; page 26, line 100, claim 17, before the word "means" insert the word *and*; page 27, line 124, claim 31, after the word "relay" insert the word *each*; page 28, line 42, claim 35, for the word "connections" read *connection*; page 29, line 86, claim 44, for the word "energizing" read *energized*; page 32, line 69, claim 72, for the word "without" read *with*; same page, line 120, claim 75, for the word "circuits" read *circuit*; page 34, line 4, claim 85, for the word "such" read *each*; same page, line 118, claim 91, for the word "group" read *groups*; same page and claim, line 122, for the word "alloted" read *allotted*; and that the said Letters Patent should be read with these corrections therein that the same may conform to the record of the case in the Patent Office.

Signed and sealed this 7th day of December, A. D., 1915.

[SEAL.]

R. F. WHITEHEAD,
Acting Commissioner of Patents.

Cl. 179—17.
